CARD PUNCHING MACHINE

Clair D. Lake, Binghamton, and Francis E. Hamilton, Endicott, N. Y., assignors to International Business Machines Corporation, New York, N. Y., a corporation of New York

Application March 26, 1941, Serial No. 385,274

23 Claims. (Cl. 164—113)

This invention relates to a combination typing and punching machine for punching record cards with information being typed on a work sheet, or to a combination calculating, typing and punching machine.

The invention, in its main aspects, resides in novel intercontrols which may be provided between record punching means and any suitable typewriter in which information is typed within spaced, predetermined fields on successive lines of a work sheet, as, for example, in the preparation of a bill. However, for purposes of the disclosure, the invention is preferably applied to apparatus which includes the typewriter-computing machine of our application, Serial No. 305,792, filed November 24, 1939. In this machine, each item of a bill is typed on a different line of a work sheet. Such an item may involve multiplication of two factors, as quantity and price. These factors are manually typed in assigned quantity and price fields of the bill sheet and entered, as a result of their being typed, in a value retaining means. After the factors have been typed, multiplying means receives the factors from the value retaining means and obtains their produce. If the item is a debit, the product is automatically typed in a debit extension field, and entered additively into a totalizer. If the item is a credit, the operator depresses a credit key and, as a result, the product is automatically typed in a credit extension field and entered subtractively, by complement addition, in the totalizer. For a simple credit amount—one not involving multiplication—the operator depresses the credit key, then manually types the credit amount in the credit extension field and, as a result, the amount is subtractively entered in the totalizer. When a plurality of lines of items have been typed on a bill and the balance is required, the operator depresses a total key and brings the total extension field of the bill to typing position. The balance is then automatically typed in the total field.

It is desired to punch tabulating or record cards with the information typed on the bill. Preferably, the information on each line of the bill is to be punched on a separate record card. One of the objects of the present invention is to provide means for insuring the punching of a separate card for each line of information typed on a work sheet. Stated differently, this object is to provide means for coordinating each line spacing operation of the work sheet with the feed of a new record card into punching position. It may also be stated as an object that means are

provided to coordinately eject a record card and line space the work sheet.

It is desired to punch the information typed in a particular field of a line of the work sheet in a predetermined, assigned field of the record card. Another object is to provide means for coordinating the spacing of a field of the work sheet to typing position with the positioning of a predetermined card field in punching position. Stated in another way, the object is to provide means for delaying the punching of information in a predetermined field of the record card until this record field and the field of the work sheet intended for receiving the typed information are both in their respective recording positions. Again, it is also an object to delay typing of the information in a field of the work sheet until the record field intended to be punched with this information is in punching position.

Another object of the invention is to provide novel classification controls to cause punching of a special designation in the record card to denote a special classification for an item being typed. Thus, the total item may be distinguished by punching a special designation in a certain column of the record card while a credit item may be distinguished by punching of a special designation in a different column of the record card. It is an object, further, to control such special classification punching by classifying means including therein the credit and total keys and credit total detecting means.

Each bill field for receiving a value has a predetermined number of columns. When the amount to be typed in the field has a less number of columns, the typewriter space bar is operated to effect intraline spacing to skip the columns of the bill field preceding the column for receiving the first significant figure. The record card field assigned for receiving the amount which is typed in the bill field has a corresponding number of columns. However, it is not desired to leave blank those columns of the record field preceding the column to be punched with the first significant figure. Hence, an object of the invention is to provide means controlled by the aforesaid skipping operation of the space bar for punching zero designations in the columns of the record field preceding the column to contain the first significant figure designation. Since the zero punching is also to be effected as a result of the operation of the zero digit key of the typewriter, the invention contemplates the alternative control of the zero punching by the zero digit key and the space bar.

Another object is to provide means for ejecting a card and feeding in a new one as a result of operation of an error key which also clears inadvertent errors out of the computer.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a plan view, showing the calculator and typewriter units, and the circuit cable to the punching device.

Fig. 1a is a chart giving the full names of certain control keys shown in Fig. 1.

Fig. 2 is a side view of a selector switch used in the machine.

Fig. 3 is a section along lines 3—3 of Fig. 1, through the product bank of the calculator.

Fig. 3a is a diagrammatic view of a readout commutator order of the total bank.

Fig. 4 is a section view showing the elusive one means of the total bank.

Fig. 5 is a section along lines 5—5 of Fig. 1, showing the drive clutch means of the calculator.

Figs. 6 and 7 are sections along lines 6—6 and 7—7, respectively, of Fig. 1.

Fig. 8 is a sectional view of the reset means of an accumulator bank.

Fig. 9 is a section through the typewriter.

Fig. 10 is a plan view of carriage-operated contacts in the typewriter.

Fig. 11 is a plan view of the punch unit.

Fig. 12 shows a fragment of a record card punched with a line of typed information.

Fig. 13 is a fragment of a bill prepared by the machine.

Figs. 20a and 20b are timing charts, and

Figs. 21a to 21g are views showing the circuit diagram.

THE BILL

Fig. 13 shows a fragment of an illustrative bill which may be prepared by the machine. The bill sheet has the usual heading area to receive the heading and, below the heading area, has the item area to receive lines of items. The item area is divided into vertical fields, which, from left to right, are the code number field (Lot No.), the quantity field (QU), the dollars orders field of the Price section, the tens and units cents orders field of the Price section, the Description field, the dollars field of the Debit section, the cents orders field of the Debit section, the dollars field of the Credit section, the cents field of the Credit section, the dollars field of the Total section, and the cents field of the total section. The heading is typed within a portion of the heading area which is a vertically upward extension of

the description field. The heading area may thus be considered as part of the description field.

The bill items may be debit or credit items, only a few of which are shown in Fig. 13. The first item of the illustrative bill is a computed debit. The item on line 4 is a computed credit while the item on line 5 is a simple credit. The net balance or total is typed below the last item.

10

RECORD CARDS

(Fig. 12)

The machine is to punch record cards with the information typed in the body of the bill. One record card is to be punched for each item and total typed on the bill. The code used in the present case is the well-known Hollerith code in which a single perforation in a card column in one of the index position 9 to 0 designates the corresponding value. The card is divided into several fields of which the three left hand fields correspond to the similarly designated fields of the bill (Fig. 13). Columns 15 to 32 are adapted to be punched with pattern card information. Columns 33 to 40 constitute the amount field which may be punched with the amount typed in the debit, credit, or total sections of the bill. To differentiate a total card from item cards, the total card will be punched in column 1 with an X or 11 perforation. To differentiate a credit from a debit card, the credit card will be punched in column 35 with the X perforation. Fig. 12 shows the card corresponding to line 1 of the bill.

30

THE TYPEWRITER UNIT

Referring to Figs. 1 and 9, the typewriter unit TU is of a well known kind, the general principles of which may be found in Patents Nos. 1,777,055 and 1,873,512. Depression of a key 10 releases a latch 11 from a cam 12, permitting the cam to be forced by a lever 13 against a friction roller 14 constantly rotated by the typewriter motor. As cam 12 engages the roller 14, it is rocked together with its carrier 15 in a direction to depress the connected link 16. This link, through linkage 17, propels the type bar 18 against the sheet on platen 19, thereby typing the character corresponding to the operated key. Towards the end of the stroke of the type bar, it strikes a universal member 20 which, through a link 21, actuates the escapement control 22 to cause an intraline or character spacing operation of typewriter carriage 23. Operation of the space bar SP also causes a similar intraline spacing.

40

The carriage return means including a key CR depression of which initiates automatic action of the carriage return mechanism, which may be of the kind disclosed in Patent No. 1,955,614.

50

The tab spacing means is of the automatic type, such as disclosed in Patent No. 1,935,436, and includes the tab key TAB, depression of which initiates automatic action of the tabular spacing mechanism to effect tab spacing in accordance with the setting of the tab stops (not shown). The tab stops are set in accordance with the required lateral spacing of the lists or vertical fields of the bill (Fig. 13) to be prepared.

60

Mounted on the frame behind typewriter carriage 23 is a normally open switch 24 (see Fig. 10). An extension 25' of the left margin stop 25 closes the switch when the carriage is returned to the beginning of the line.

70

The carrier 15 of each of the digit keys has an insulating roller 26 for engaging the adjacent

75

spring blades 27, upon operation of the digit key, to close inner and outer calculator control contacts 28 and 28' in succession. Punch control contacts 28p are arranged to close substantially simultaneously with contacts 28'. Similarly, depression of the space bar closes associated contacts 28 and 28p. The carriage return key, when depressed, closes associated contacts 28, and the depression of the tab key similarly closes a pair of related contacts 28.

A solenoid 30 is associated with each digit key, the carriage return key, the tab key, and the space bar. Energization of a solenoid 30 acts through linkage 31 to depress the associated element automatically.

The typewriter unit also is provided with several control keys including an error key EK, a credit key CK, a total key TK, and a total and reset key TRK, each closing contacts which are shown in the circuit diagram, Fig. 21a.

Also included in the typewriter unit, in addition to the usual typewriter motor switch SW-T, are a three-pole switch SW-L, a product bank reset switch SW-PR, and a summary punch gang switch SW-SP (see Figs. 1 and 21a).

The functions of the switches, the special keys, the key contacts, and the key solenoids will be explained hereinafter in detail in connection with the circuits.

THE CALCULATOR UNIT

Drive.—Referring to Figs. 1 and 5, the motor M-C rotates a shaft 32 to which is fixed a toothed driving clutch disk 33 adapted to be engaged by a clutch dog 34 carried by a clutch arm 35 fixed to the calculator cycle shaft 36. The clutch dog and arm are normally latched by a lever 37 and associated rebound latch 37'. The latch lever is provided with an armature portion 38 associated with a clutch magnet 40. Energization of the clutch magnet releases lever 37 from the clutch dog and arm, causing the clutch dog to engage a notch of the driving disk 33 and thus couple shaft 36 to shaft 32 for at least one revolution.

Accumulator banks.—The calculator unit has two accumulator banks ACC-P and ACC-T, respectively the Product and Total banks. The general construction of these accumulator banks is similar to that disclosed in Patent No. 1,976,617. Briefly, shaft 36, through gears 41 (see Fig. 3) rotates a shaft 42 acting, through gears 43, to rotate a shaft 44. The latter shaft, through individual clutch connections selectively rendered effective by double coil entry magnets CM, one for each order, drives gears 45, each meshed with a gear 46 on an indicator wheel 47, rotatably mounted on a shaft 48. Gear 45 is meshed also with a gear 49 of the rotor 50 associated with the same denominational order or column of the readout commutator PRO (see Fig. 21b) of the product bank as the indicator wheel. This product bank commutator is similar to the readout commutator of Patent No. 1,976,617. The gear ratio between shaft 44 and the rotor 50 is such as to cause the rotor to make one revolution for two of the indicator wheels. The rotor 50 of each column has two diametrically opposite brushes or feelers 51, alternating during successive cycles, in engaging the collector ring 52 of the column and the segments 53-0 to 9 common to two adjacent columns.

The product bank is used to obtain the product of two factors, which, for the illustrative bill (Fig. 13), are the numbers under the headings "quantity" and "price."

A total bank ACC-T is used to obtain a balance of the items on one or more bills. The items may be either debit or credit items. The debit may be considered as the plus item, while the credit item may be considered as the minus item. The debit amounts are entered additively or as plus numbers into the total bank, while the credit amounts are entered subtractively, as complements. The readout commutator PRO

10 (Fig. 21b) of the total bank is similar in principle to those disclosed in Patents Nos. 2,007,375, and 2,045,437. One order of this commutator is shown diagrammatically in Fig. 3a and comprises axially spaced plus and minus collector rings respectively wiped by plus and minus brushes carried by rotors, insulated from each other but which are commonly operated by one gear 49 in step with the operation of the indicator wheel 47 of the same order. There are 15 two diametrically opposite minus brushes and two similarly disposed plus brushes, and while one plus brush is wiping the plus collector ring, the opposite plus brush is traversing the commutator segments 0 to 9. The minus brushes are 20 one step behind the plus brushes, so that with the plus brush on the "0" segment, one minus brush is on the "9" segment and the opposite minus brush on the minus collector ring. Similarly, with the plus brush on the 1, 2, 3, . . . or 25 9 segment, the minus brush is on the 0, 1, 2, . . . or 8 segment.

In entering the complement of a credit item into the total bank, the elusive "1" must be added to the units order. The elusive "1" means is such as disclosed in Patent No. 1,976,617. Referring to Fig. 4, the elusive "1" magnet ELM, upon energization, releases armature latch 55 from the rockably mounted arm 56 which supports the carry over pawl 57 (also see Fig. 3) engaged with the carry arm 58 of the units order wheel 47. The release of arm 56 permits a spring 59 to rock the arm rearwardly against the carry bail 60. After the digit entry portion of an accumulator cycle (see Fig. 20a), a cam 61 (Fig. 4) on shaft 42 acts, through a lever 62 linked to bail 60, to 30 rock the bail forwardly, thereby returning the carry arm 56 into latching engagement with the armature latch 55 of the meanwhile deenergized magnet ELM. As the arm 56 is restored, the pawl 57 engages a tooth of cam 58 to move the units order wheel 47 one step, adding the elusive "1" to the units column of the total bank.

The carry over mechanism between adjacent orders of the accumulator banks is such as disclosed in Patent No. 1,976,617 and includes carry cams 58 and pawls 57 for each of different orders, their carriers 56, latches 55, bail 60, link 62, and cam 61. When an indicator wheel, during the entry period, moves from 9 to 0, a high tooth of the associated carry cam 58 rocks the follower pawl 57 to an extent sufficient to cause a laterally extending ear 57' thereof to rock the latch 55 of the next higher order downwardly so as to release the arm 56 of the latter order. The 40 operation of bail 60, after the entry period, rocks the released arm 56 to cause the pawl 57 carried thereby to advance the latter order one step.

Referring to Figs. 1 and 8, the reset means for the accumulator banks is of the type disclosed in Patent No. 2,049,690. There is a reset magnet 70 RM for each bank, energization of which causes rotation of the shaft 48 of the indicator wheels of the related bank to effect resetting of the indicator wheels and the other, connected elements of the bank. The means for effecting ro-

tation of the shaft 48 comprises a gear 63 fixed to one end of the shaft and meshed with a gear 64 freely mounted on a shaft 65. Rigid with gear 64 is a clutch collar 66 having a single notch 66' adapted to receive the nose of a clutch dog 67 carried by an arm 68 fixed to shaft 65. During rotation of shaft 65, the tail of the clutch dog engages the roller 69 provided on one end of a lever 70 which is normally latched up by armature 71 of the reset magnet RM. During each revolution of shaft 65, the engagement of the tail of the clutch dog with roller 69 cams the nose of the dog outwardly as it traverses the notch 66' of the stationary clutch collar 66. When the magnet RM is energized, lever 70 is unlatched and moves clockwise (Fig. 8) so that roller 69 is no longer in the path of the tail of clutch dog 67. As a result, when the nose of the clutch dog next reaches notch 66', it is free to move into the notch and, in so doing, it couples the gear 64 to the shaft 65 for a single revolution. Gear 64, during its revolution, acts through gear 63 to rotate shaft 48 to reset the bank associated with the energized reset magnet.

Rigid with driven gear 64 is a cam 71' (Fig. 1) which, during the revolution of this gear, cams a bail 72 (also see Fig. 8) counterclockwise, causing an insulating lug 72' thereof to depress the lower spring blade 73 carrying one of the points of the normally closed contacts RMa. Thus, during reset of a bank, the associated contacts RMa are momentarily opened.

The reset magnet of the total bank may be characterized as RM-T, and that of the product bank as RM-P. It should also be noted that similar elements of both banks may be distinguished by appending the letter P to the common reference character to denote association with the product bank and by the letter T to denote association with the total bank. Further, denominational orders of similar elements may be distinguished by appending to the common reference character, the letter *u* to denote the units order, the letter *t* to designate the tens order, the letter *h* to indicate the hundreds order, the letters *th* to designate the thousands order, the symbol 10*thd* to designate the tens of thousands order, and so on. Further, in the description of relays, the relay contacts may be characterized by the reference number or character of the relay magnet followed by a letter *a*, *b*, *c*, etc.

Cam contacts, impulse emitters, make and break contacts

Referring to Figs. 1 and 6, the accumulator cycle shaft 36 extends past the total bank ACC-T, and near its right-hand end carries two make and break contact cams 74 for operating make and break contacts 75. Shaft 36 drives, in one-to-one ratio, gears 76 carrying the feelers 77 (see Fig. 21d) of two impulse emitters E+ and E-, respectively, the plus or debit and the minus or credit emitters. Shaft 36 also drives, in one-to-one ratio, through gearing 78 (also see Fig. 7), the shaft 65, previously referred to in the description of the reset means. Shaft 65 carries a plurality of cams A' for operating the several A cam contacts (see Fig. 20a). The make and break contacts 75, the emitters E+ and E-, and the A cam contacts all operate on a "16" point cycle basis, and this "16" point cycle may be referred to as an accumulator cycle (Fig. 20a).

Geared one-to-three to shaft 36 is a shaft 79 which drives, in one-to-one ratio, the feelers 80 (see Figs. 1, 6 and 21b) of auto type emitters

E-T and E-P. Driven one-to-one by shaft 79 is a shaft 81 on which are two make and break cams 82 for operating the make and break contacts 83. The shafts 79 and 81 carry the cams R' for operating the R cam contacts. The latter cam contacts, emitters E-P and E-T, and make and break contacts 83 all operate on a "14" point cycle basis, and this cycle may be referred to as the readout cycle (Fig. 20b). As indicated by Figs. 20a and 20b, each read out cycle is coextensive with a series of three accumulator cycles. The readout cycle thus takes three times as long as an accumulator cycle, and the speed of the readout cycle means is such as to suit the requirements for accurate operation of the typewriter mechanism.

As will be brought out further in connection with the description of the circuit, the points of the readout cycle marked "1", "2" . . . "8" correspond to columns of the accumulator banks and designate the points of the readout cycle at which corresponding columns of the banks are read out. The points "9" to "1" of the accumulator cycle represent the points at which energization of a control magnet CM causes entry of values "9" to "1" into the associated order of the accumulator bank, and the cycle interval "9" to "1" may be referred to as the entry portion of the cycle.

Selector switches.—Also included in the calculator unit are three selector switches SW-#1, SW-#2, and SW-#3. The switch SW-#1 is used during the setting up of values under control of the typewriter keys, the switch SW-#2 is used during the multiplying operation, and the switch SW-#3 is used to correlate controlling operations of the calculator unit to the tab spacing operation of the typewriter. The construction of each selector switch is similar and shown in Fig. 2. The selector switch comprises a common contact segment 84 and contact segments 85 wiped by a feeler 86 fixed to a shaft 87. On this shaft is a ratchet wheel 88 engaged by a holding pawl 89 which prevents the shaft from being restored, in a counterclockwise direction, by a spring 90, to the home position, which is one step behind the "1" segment. While the feeler is in home position, an insulating roller 91 on its rear end holds a pair of contacts SWa and SWb open. As soon as the feeler departs from home position, these contacts close. The holding pawl 89 of the switch is released from the ratchet 88, to permit restoration of the feeler, upon energization of a release magnet SWR. The ratchet 88 is also engaged by an actuating pawl 92 carried by the armature lever 93 of the stepping magnet SWM. Each time magnet SWM is energized, it causes pawl 92 to advance the feeler 86 one step. The construction of the ratchet 88 is such as to prevent its advance and advance of the feeler 86 from segment 85-10 or from its "0" position should an impulse be received by the stepping magnet SWM while the feeler is in the "10" position.

CARD PUNCHING UNIT

The punching unit is of the kind disclosed in Patent No. 1,976,618 and comprises rigidly united pattern card frame 310 and work card frame 311 (Fig. 11). Between the adjacent sides of these frames is a rack 312 (also see Figs. 14, 15 and 19) carrying oppositely extending brackets 313 and 314 respectively, mounting a rear pusher 315 for the pattern card P resting on a surface of frame 310 and a rear pusher 316 (Figs. 11 and 15) for the work card W resting on a surface of the frame

311. A front bracket 317 is secured to the rack and carries a hold-down clip 318 for the leading edge of the pattern card and an abutment 319 for the leading edge of the work card. Rack 312 is part of card carriage and is actuated, in a manner which will be brought out later, through forward and return strokes. Pusher 315 and gripper 318 force the pattern card to reciprocate with the rack. The work card is forced by pusher 316 and abutment 319 to move with the rack through its forward stroke, at the end of which it is automatically ejected, as will be described later. Within the pattern card section is an analyzer comprising a common contact roll 320 and a column of sensing brushes 321, one for each index position of the card. These brushes are in operative position during the forward stroke of the card carriage and when a perforation is sensed by a brush in an index position of the pattern card, a duplicating circuit, which will be traced later, is established to energize a magnet 322 (Figs. 11, 14, and 15). There is one magnet 322 for each index position and the energization of each magnet results in the punching of a corresponding index position in the work card. In the present case, the pattern card is perforated with the common information to be duplicated in columns 15 to 32 of each work card pertaining to the same account. According to the present invention, the lot number, quantity, price and amount fields of the work card are punched under control of the means for selecting the typing elements for typing the values on a line of the bill. This automatic control of the punching means is effected, as will be described later, through means including the magnets 322 and results in punching each work card with the values typed on a line of the bill.

The armature lever 323 of each magnet 322 is swiveled to the stem of one of the keys 324, and energization of a magnet causes depression of the related key. Within the work card section is a column of punches 325 and coacting die block 326 for punching one column of the work card at a time. When a key 324 is depressed, through a lever 327 it advances an interposer 328 which rests on the head of a punch 325. The advance of the interposer places its upper edge below the tip 329 of the hammer 330 (Figs. 14 and 15), so that depression of the hammer will serve, through the advanced interposer, to depress the punch for perforating the selected index position of a card column. The hammer is connected by a linkage 331 to the armature 332 of a punch-operating magnet 333. Energization of this magnet results in depression of the hammer to operate the selected punch or punches. Magnet 333 is energized as a result of advance of any of the interposers 328. When any interposer is advanced, it rocks a bail 334 counterclockwise (Fig. 14) to elevate the hook end of an arm 336 connected to the bail. The hook end of the arm thereupon acts, through insulation, to close a switch 337. This completes a circuit, traced later, through magnet 333. Magnet 333 operates linkage 331 to depress hammer 330 and cause punching of the selected designation or designations. As an incident to this operation, a lug 338 on the lower link 331 releases hook 336 from switch 337 which thereupon opens and deenergizes magnet 333.

Escapement mechanism such as in Patent No. 1,426,223 is used to advance the card carriage one column width after each punching operation is performed. Referring to Figs. 15 and 19,

a bail 339 pivoted on a pivot shaft 340 is rocked downwardly upon depression of any interposer during punching operation. Bail 339, through a screw 341 rocks a lever 342 about pivot 340, in the same direction; clockwise, as viewed in Fig. 19. The rocking of bail 339 and lever 342 is resisted by a compression spring 343. Lever 342 has a screw 344 bearing on a projection of a two-armed lever 345. A spring 346 between a stud 347 of lever 345 and an ear of lever 342 urges lever 345 to follow 342 in a clockwise direction. The lever 342 has a pin 348 in a slot 349 of escapement pawl 350 which is connected by a spring 351 to stud 347 of lever 345. The spring 351 tends to rock the escapement pawl counterclockwise, as viewed in Fig. 19. Pawl 350 is mounted on shaft 340 with horizontal play. Lever 345 has a stud 352 engaged in a notch of holding pawl 353. Fig. 19 shows the pawls in normal position with respect to escapement teeth of rack 312. During the punching operation, bail 339 and lever 342 are positively rocked clockwise (Fig. 19) by engagement with an interposer. Spring 346 causes lever 345 to follow lever 342. Pin 348 on lever 342 lifts escapement pawl 350, while pin 352 of lever 345 depresses holding pawl 353. The nose of pawl 353 engages a notch of rack 312 before the nose of escapement pawl 350 fully releases the rack. Thus, the rack and, hence, the card carriage remain at rest during punching operation. When the punch operating hammer 330 and the interposers are restored after punching has been completed, the spring 343 returns bail 339 and lever 342 counterclockwise (Fig. 19). Screw 344 rocks lever 345 in the same direction. Pawl 350 has, meanwhile been moved towards the left (Fig. 19), above the next escapement tooth of rack 312, by spring 351. As levers 342 and 345 now rock counterclockwise, holding pawl 353 is raised, releasing pawl 353 while pawl 350 is lowered. The rack 312 then moves to the right (Fig. 19) through its usual motor spring (not shown) until pawl 350 returns to the same position with respect to pivot shaft 340 as in Fig. 19. This movement of the rack is an escape through one tooth distance equal to movement of the carriage through one column width.

As stated before, the total card is distinguished by an X hole in column 1. The punching of the X hole in column 1 causes skipping of the lot number, quantity, and price fields. The last column of any card to be punched is column 40. The remaining columns 41 to 80 may be skipped. Both the skipping as a result of the punching of an X hole in column 1 and the skipping of columns 41 to 80 is controlled by a skip bar 360 attached to one side of the escapement rack 312 (see Figs. 19 and 19a). The upper edge of the skip bar has low, intermediate, and high levels spaced according to the requirements of the skip feed for a particular job. In the present case, the skip bar has an intermediate level extending from column positions 1 through 14, followed by a low level extending from columns 15 through 40, followed, in turn, by a high level extending from column 41 through 80. Resting on the upper edge of the skip bar is the inclined end of the well-known skip lifter 361 which also underlies the escapement pawl 350. When the lifter is shifted transversely while lying on the intermediate level of the skip bar, it is elevated sufficiently to release pawl 350 from escapement rack 312, permitting continuous advance of the latter. The operation of the X key, in a well known manner, described in detail in Patent No.

1,426,223, causes punching of an X hole in the card column and, also, shifts the skip lifter transversely. With the intermediate level of the skip bar under the transversely shifted skip lifter, the lifter is raised sufficiently to maintain the escapement pawl 350 clear of rack 312. Thus, if column 1 be punched with an X hole, then upon return of holding pawl 353 to normal release position and with pawl 350 being held by the skip lifter from reengaging the rack 312, the carriage escapes to column 15 position, in which the low level of the skip bar is under the skip lifter. The skip lifter drops, permitting pawl 350 to reengage the rack and arrest the carriage in column 15 position. The next operation of a key 324 restores the skip lifter to normal, retracted position as described in detail in Patent No. 1,426,223. When the carriage reaches column 41 position, the high level of the skip bar moves under the skip lifter and, although the latter is then in retracted position, it is sufficiently elevated to release pawl 350 from rack 312. The carriage then escapes past its last column position at which point it is automatically ejected.

The card carriage may be released at any time by energization of a release magnet 322R (Fig. 11) which, through its armature lever 323, depresses the usual release key R (see also Fig. 17). The key R rocks a lever 363 to shift a bar 364 to the rear. Bar 364 is inclined at its left end (Fig. 17) to cause the bar to be cammed upwardly by its supporting plate 365. The bar 364 lies under skip lifter 361 and when the bar rises, it elevates the lifter to cause release of the escapement pawl 350 from the rack 312. As a result, the card carriage moves to its card eject position. Just as the carriage moves into this position, a pin 366 fastened to the carriage strikes the left end of the bar 364 and restores it to inactive position.

The usual floating cam contacts 370 (Fig. 19) are provided. The structure and operation of the contacts are fully disclosed in Patent No. 2,063,475. Briefly, the cam contacts are normally closed, with the upper blade engaging, through insulation, with a stud on the end of a pivoted arm 371. A portion of this arm rests on top of pawl 350, so that when the pawl is raised, it rocks the arm to open contacts 370. This occurs as an incident to each punching operation since, as explained before, the pawl 345 is raised above rack 312 during the first part of each punching operation. The opening of the contacts 370 breaks the duplicating circuit, which will be traced later. The contacts reclose after the card carriage has moved to its next column position. When pawl 350 is raised by the skip lifter 361 during either of the skipping and release key operations, the contacts 370 remain open to eliminate the possibility of the duplicator circuits being formed until the skip or release feed of the card carriage is terminated.

When a card carriage moves past the last column position, a lug 372 fixed to the escapement rack 312 strikes the upper arm of a lever 373 causing the lower end of the lever to close last column contacts 374. In a manner which will be explained later, the eventual effect of closure of contacts 374 is to cause energization of stacker magnet 376 (Fig. 16). The magnet 376 causes ejection of the card in last column position and the depositing of the card in a receiving hopper 389. The eject means is such as described in detail in Patent No. 1,916,965. Stated generally, the eject means comprises a pair of jaws 378 and

379 normally closed by a flat spring 380, with the upper jaw 379 abutting a fixed stop 381 and spaced thereby from the lower jaw. As the punched card moves to last column position, its leading edge moves between the gripper jaws. The gripper unit is at this time latched in normal position by a latch lever 382 engaged with a shoulder 383 of the rear arm of the lower jaw 379. The latch lever is in front of a projection 384 of a link 385 connected to the armature of stacker magnet 376. When the magnet is energized, it acts through link 385 to release latch lever 382 from the gripper unit, permitting the shaft of the gripper unit to be turned counterclockwise, as viewed in Fig. 16, by the movement of gear train 386 now actuated by a rack 387 under the influence of a spring 388. As the gripper unit starts to turn counterclockwise, its jaws close to grip the card. The gripper unit then ejects the card to the receiving hopper 389. The jaws of the gripper are opened to release the card as it reaches a position above the hopper by means of the stop pin 391 striking a part of the lower jaw. When the card has been completely ejected, rack 387 (see also Fig. 18) reaches a position in which its forward end acts through an insulation piece on a blade of a switch 392 to close this switch. Consequently, a circuit is established in a manner which will be traced later through a clutch trip magnet 393 (Fig. 14). This magnet attracts its pivoted armature structure 394. The armature structure includes an arm 395 which engages a pin 396 of clutch dog 397 to force the tooth of the clutch dog into engagement with the ratchet clutch 398 on the motor driven shaft 399. The clutch dog remains engaged with the clutch 398 by the action of a toggle linkage 400 connected to the clutch dog. Shaft 399 is driven by a motor 401 which is not set in operation until the clutch dog has first been engaged with the ratchet 398 by energization of trip magnet 393. When the armature structure of the magnet is attracted, an arm 402 thereof (see Fig. 15) opens contacts 403 and closes contacts 404. The contacts are latched in this condition by a latch lever 405 which is released in a known manner at the end of a cycle of shaft 399. The closing of the lower contacts 404 forms a circuit through motor 401 in a manner which will be traced later. The ratchet clutch is now in operation and through the clutch dog actuates the gear 406 which is meshed with a lower toothed edge of a rack 407. Gear 406 is rotated counterclockwise and moves the rack 407 to the left (Fig. 14). Attached to the right hand end of the rack is a bracket 408 (Fig. 11) carrying the picker knife 409 which, when the rack is moved to the left, feeds the bottom card of the stack of blank cards in supply hopper 410 out of the mouth of the hopper and onto the card carriage. In order to receive the card, the card carriage must be in its rearmost position or in its first column position. For this purpose the upper edge of rack 407 is meshed with a gear 411 (Fig. 14) which through a one-way driving connection actuates an arm 412 fixed to a shaft 413. The shaft carries at the opposite end a gear 415 (Fig. 15) meshed with the lower edge of escapement rack 312. When rack 407 is moving to the left, as viewed in Fig. 14, it rotates the gear 415 clockwise causing the rack 312 and, hence, the card carriage to move to the right into its first column, new card-receiving position.

When rack 407 moves to the left, it also acts

on ejector rack 387 to move the latter in the same direction. Through gearing 386, the eject gripper is restored to normal, and card receiving position in which it is relatched by lever 382. Spring 388 also is compressed to store energy for subsequently operating the eject means.

When there are no cards in the supply hopper, hopper contacts 418 (Fig. 15) spring open. Also shown in Fig. 15 are card lever contacts 420 which are closed by card lever 421 when a card is in position on the card carriage. The card is then under the left, bent end of lever 421 and holds it in clockwise position, closing contacts 420.

Connected to the card carriage are the usual commutator brushes 422 and 423 (Fig. 11) which respectively wipe the column commutator contacts 424 and the common return strip 425 of a commutator block. For each column position of the carriage, a brush 422 is engaged with a corresponding column contact 424.

CIRCUITS AND OPERATION

The machine is connected to a current service line through a common plug 100 (left of Fig. 21a). Binding posts *b* are provided, as indicated in Figs. 21a and g, and the circuit connections to and from the binding posts may be referred to as connections *b*-1, *b*-2, *b*-3, etc. The circuit wire connections from the typewriter unit and the calculator to the punch unit extend through cable 9 and cable 9a (a portion of which is indicated in Fig. 1) and lead to the *p* binding posts of the punch unit (see Fig. 21g). The wire connections between the calculator unit and the typewriter are in cable 9.

If it is desired to run the typewriter by itself, typewriter switch SW-T is closed (Fig. 21a), closing the circuit of typewriter motor M-T from plug 100 through connection *b*-1, switch SW-T, motor M-T, connection *b*-2, back to the plug.

It will be assumed that the typewriter is not to be run by itself but together with the calculator and punch; hence, switch SW-T is open.

Power is placed in opposite sides 101 and 102 of the calculator by closing switch SW-L (Fig. 21a), connecting binding parts *b*-3 and *b*-4 to binding parts *b*-1 and *b*-2 which lead to the plug 100.

As soon as power is on opposite sides 101 and 102, calculator motor M-C (Fig. 21a) starts running.

When the punch unit is to be operated with the typewriter and calculator, main punch switch MS (Fig. 21g) is closed, connecting punch current sides 452 and 453 to calculator current sides 101 and 102.

Having placed the bill sheet in the typewriter and the corresponding pattern card P in the punch unit and having made required plug connections in the punch which will be explained later, the operator depresses key EK (Fig. 21a). Closure of the right side of contacts EKA establishes the following circuit:

Coil 143 circuit.—Line 101, post *b*-34, the right side of contacts EKA, post *b*-35 (turn to Fig. 21b), coil 143, line 102.

Coil 143 closes contacts 143b (Fig. 21g) completing the following circuit:

Release magnet 322R.—Line side 453, post *p*-18, contacts 143b, post *p*-19, release magnet 322R (also see Fig. 11), and through resistance to line side 452.

Energization of magnet 322R, in the manner

75

explained before, causes the card carriage to escape to its last column position in which it closes contacts 374 (see also Fig. 19). Closure of contacts 374 energizes last column relay coil 5 455 (Fig. 21g). Coil 455 closes contacts 455a, energizing stacker magnet 376 (also see Fig. 16). Energization of magnet 376, in the manner explained before, causes operation of card eject device 378-379, during which rack 387 moves 10 to the right, closing contacts 392 (Fig. 18). Closure of contacts 392 completes the following circuit (Fig. 21g):

Clutch magnet 393 circuit.—Line side 453, contacts 392, last column relay contacts 455b, connected posts *p*-6 and *p*-5, clutch trip magnet 393, safety contacts 456a, to line side 452.

Energization of magnet 393, as previously described, clutches the pawl 397 to drive ratchet 398 (see Fig. 14) and also opens contacts 403 while closing contacts 404 (also see Fig. 15).

Closure of contacts 404 establishes the punch unit motor circuit as follows (Fig. 21g):

Punch motor 401.—Line side 453, contacts 404, motor 401, safety contacts 456a, to opposite line side 452.

With the motor 401 set in operation, the card picker rack 407 (Fig. 14) is moved to the left, causing the carriage to move to the right. The picked 409 feeds the bottom card from supply hopper 410 to the card carriage. Also, the card eject means is brought to normal condition, as explained before. At the end of a cycle of the shaft 399, the contacts 403 and 404 are restored to normal condition by releasing latch lever 405, and the clutch pawl 397 is restored to ineffective position, as explained in detail in Patent No. 1,976,618. Opening of contacts 404 stops motor 401.

As the ejector rack 387 returned to the left to normal position, contacts 392 opened, breaking the circuit of clutch magnet 393. As a result of the above operations, a card W is in column 1 punching position on the card carriage.

It may be noted that key EK is depressed preparatory to typing the first item line of the bill, so as to feed a card, into punching position. Key EK, as will be brought out later, is also the error key, and when an error is found in the typing of an item, this key is depressed, causing eject of the card then on the card carriage and feeding in of a new card.

As the card is fed to column 1 position, it closes card lever contacts 420 (Fig. 15), establishing the circuit of card lever relay coil 451. Coil 457 closed stick contacts 457a to hold this coil energized until the next eject and feed cycle. With card lever relay contacts 457b and magazine contacts 418 (also see Fig. 15) closed, the following circuit makes:

Magnet 458 circuit.—Line 101, post *p*-3, contacts 418 and 457b, post *p*-4, magnet 458, to line 102.

Magnet 458 closes contacts 458a (Fig. 21a) establishing the circuit of typewriter motor M-T, as follows:

Motor M-T.—Plug 100, post *b*-1, contacts 458a, the left hand blade of switch SW-L, motor M-T, post *b*-2, back to plug 100.

The typewriter is now ready for operation. It may be noted that until the first card was placed in punching position as a consequence of depression of key EK, card lever contacts 420 were open, card lever relay 457 was unenergized and the circuit of coil 458 could not make. Hence, the typewriter operation could not start until

the first card was fed to punching position. It may be noted further, that when cards are not in hopper 410 or when a card fails to feed properly to the card carriage, the circuit of magnet 458 will not be made and the typewriter motor circuit will be opened by the breaking of contacts 458a. The typewriter operation will thus be interrupted when cards are exhausted or fail to feed properly.

When it is desired to operate the typewriter and calculator without the punch unit, the punch control gang switch SW-SP is left in "off" position (see Fig. 21a). In this "off" condition, the switch blades #1, #2, #3, #4, and #5 are in full line positions. With switch blade #3 in "off" position, a circuit is closed from line 101 (Fig. 21a), to post b-73, through this switch blade, connection B-14 (turn to Fig. 21g), and magnet 458 to line 102. Contacts 458a close to permit the typewriter motor to be set running upon closure of switch SW-L (Fig. 21a), independently of the punch unit.

When the typewriter, calculator, and punch are to operate together, the gang switch SW-SP is set in "on" position and switch blades #1, #2, #3, #4 and #5 are in dotted positions (Fig. 21a).

Operation of switch SW-#3

Fig. 21f shows the circuit connections through switch SW-#3 (Fig. 2 shows the mechanical construction), which is used to correlate the vertical fields of the bill with the operation of the punch in correlated fields of the card W and with the operation of the calculator. To each of the ten segments of switch SW-#3 is connected a plug socket 103 which may be wired by a plug connection 104 to any of the five plug sockets 105. Each segment of the switch, as well as the connected plug socket 103, corresponds to one of the fields of the bill, as indicated in Fig. 21f. For the present case, the lot number socket 1 is connected to socket 105-1, the quantity field socket 103-2 is connected to socket 105-2, the dollars debit socket 103-6 is connected to socket 105-3, the dollars credit socket 103-8 is connected to socket 105-4, and the total socket 103-10 is connected to socket 105-5.

The sockets 103 are successively connected to common line 101 by stepping the feeler 86 of the selector switch along segments 85 in accordance with the tabular spacing of the bill and, therefore, in accordance with the fields of the bill brought to typing position. In order that the selection of sockets 103 by switch SW-#3 be repeated for each line of the bill, the feeler of this switch is restored to home position as an incident to each carriage return operation. When the carriage return key CR is operated, key contacts 28-CR close, forming the following circuit (Fig. 21a):

Switch SW-#3 release magnet.—Common line 102, through release magnet SWR-3, connection b-36, key contacts 28-CR, connection b-37, common line 101.

When the carriage reaches the beginning-of-the-line position, contacts 24 (Fig. 10) close, as explained before. These contacts are in parallel with the key contacts 28-CR, and closure thereof forms a parallel circuit through the release magnet. Thus, even if the carriage return operation were effected manually instead of as a result of depression of the carriage return key, the closure of contacts 24 would result in energization of magnet SWR-3. Energization of this magnet causes the return of the feeler 86 to home posi-

tion, one step behind the "1" segment of the switch SW-#3.

The first operation on the bill sheet is to type in the heading. Since the description field, along 5 a vertical extension of which the heading lies, corresponds to socket 103-5, which is not connected to any of socket 105, the typing in the heading will not affect the operation of the calculator unit. After typing the heading, the operator manually initiates a carriage return operation and spaces the bill sheet to position the first item line of the bill at the typing line. As a result of the carriage return operation, the feeler of switch SW-#3 is restored to home position. The tab key is then depressed to tabulate the carriage to the first column of the lot number field. The depression of the tab key closes key contacts 28-TAB to form the following circuit (Fig. 21a) through the stepping magnet SWM-3 of switch SW-3:

Switch SW-#3 stepping magnet.—Line 102, through magnet SWM-3, connection b-38, key contacts 28-TAB, connection b-37, line 101.

Energization of magnet SWM-3 steps the feeler 86 to segment "1" of switch SW-#3, connecting the socket 103-1 to common line 101 (see Fig. 21f). As socket 103-1, corresponding to the code number field, is connected to socket 105-1, a circuit is closed through a coil 460.

Coil 460 closes its contacts 460a (Fig. 21g) establishing a circuit through multi-contact relay magnet PM, as follows (begin with Fig. 21g):

Magnet PM circuit.—Line 102, magnet PM, contacts 460a, connection b-72 (turn to Fig. 21a), switch blade #4, connection b-71, to line 101.

Magnet PM closes the group of contacts PMa individually in series with the key contacts 28p (Fig. 21g).

The operator now proceeds to type the lot number. As a digit key is depressed to type a number, it causes closure of related key contacts 28p (see also Fig. 9). Assuming the "2" digit key 10-2 has been depressed, the following circuit is established (Fig. 21g):

Punch selection circuit.—Line 101, post b-66, the common of contacts 28p, contacts 28p-2, the connected contacts PMa, key magnet 322-2 (see also Fig. 11), through resistance to line side 452.

Energization of magnet 322-2 causes punching 50 of a "2" perforation in the card column which is in punching positions.

Similarly, all the other digits of the lot number are typed in the lot number field of the bill and their designations punched in columns 1 to 6 of 55 the card W (Fig. 12). When the recording of the lot number is completed, the operator depresses the tab key to bring the first column of the quantity field to typing position. This tabular spacing operation again forms the circuit of magnet SWM-3, causing the feeler of switch SW-#3 to move to segment "2." Thereupon, the following circuit is established (Fig. 21f):

Coil 110 circuit.—Line 101, through position "2" of switch SW-#3, socket 103-2, a plugwire 104 to socket 105-2, coil 110, line 102.

Energization of coil 110 closes contacts 110a to form the following circuit (lower part of Fig. 21e):

Coil 111 circuit #1.—Line 101, contacts 110a, coil 111, line 102.

Coil 111 closes contacts 111a (Fig. 21a). Closure of these contacts is a condition precedent to the completion of circuits, traced later, for entering values typed into the quantity, price, amount and credit fields of the bill (Fig. 13)

into value retaining means provided in the calculator unit. Thus, energization of coil 111 conditions the calculator unit to receive values typed on the bill. In addition, coil 111 closes contacts 111d (Fig. 21g). These contacts are in shunt with contacts 480a and similarly establish the circuit of relay magnet PM. Hence typing of the quantity and price will cause punching of the equivalent perforations in columns 7 to 14 of card W.

THE VALUE RETAINING MEANS

The value retaining means comprises a bank of relays including eight columns of value retaining coils 114 (Fig. 21c) and associated relay contacts 114a and b. For convenience, the bank of 114b contacts is shown separately in Fig. 21d. During the typing and punching of the quantity, the hundreds, tens, and units orders of quantity digits are entered, respectively, into the first or left-hand column of the value retaining bank, the second, and third columns. During typing of the price factor, the successive orders of price digits are entered into the fourth, fifth, sixth, seventh, and eighth or right-hand column of the value retaining bank. During typing in the debit or credit section of the bill, the eight columns of the value retaining bank correspond to the eight columns of the amount or the credit section, and will be successively set up, from left to right, in the same order as the digits are typed in the corresponding columns of the debit or credit section. Each column of the value retainer bank includes ten value coils 114 and related 114a and b contacts, corresponding to digits 0 to 9, as indicated for the left hand column in Figs. 21c and d.

RELATING TO ENTRY INTO THE VALUE RETAINED BANK

The entry means includes a pair of relay coils 115 (upper right of Fig. 21a) for each digit key. The energization of the pair of coils 115, corresponding to a digit, closes a row of eight 115a contacts (Fig. 21c) which are in series with the eight value coils 114 of the corresponding digit row of the value retaining bank. The closure of the 115a contacts partially closes the circuits of the related value coils, but only one of these circuits at a time may be completed, depending on the operation of the selector switch SW-#1. This switch functions to correlate the columns of the retaining relay coils successively with the corresponding columns of the bill into which the digits to be entered are being typed. In effect, the switch SW-#1 successively places the columns of the value retaining bank under control of the digit keys just as the intraline spacing of the corresponding columns of the bill successively places them in condition to be typed under control of the digit keys.

Concerning switch SW-#1.—Initially, the feeler 86 of switch SW-#1 is in home position, one step behind the "1" segment 85 (see Fig. 2). When a digit key is operated to type the digit in the first column of the quantity, amount, or credit section of the bill, the stepping magnet SWM-1 of switch SW-#1 is energized to step the feeler 86 to the "1" segment which is in the circuit of the first or left hand column of coils 114 (see Fig. 21c). The switch reaches this position immediately before the operation of the key results in the energization of the related key coils 115 and the consequent closure of the row of contacts 115a. As a result of the po-

sitioning of switch SW-1 and closure of 115a contacts, an initiating circuit is formed through a coil 114 in the left hand column of the retaining relay bank. The switch SW-1 selects the column of the value bank of which a coil 114 is to be energized, while the contacts 115a select, in this column, the particular coil corresponding to the digit which is being typed by the active digit key. The energized coil 114 closes its 114a contacts to form a stick circuit, operative after opening of the momentarily closed 115a contacts.

When the second digit is typed, the switch SW-#1 is stepped to position "2" to select the second column of the value retainer bank, and so on for the third, fourth, and to the eighth column of the retainer bank. If, instead of operating a digit key, the space bar SP is operated, the switch SW-1 will be similarly stepped along, thereby maintaining the columns of the retaining relay bank coordinated with the intraline spacing of the corresponding orders of the bill columns in which the value to be entered is being typed.

Entry of quantity and price factors.—To simplify the explanation, assume that the quantity or multiplier factor is 123 and the price or multiplicand factor is 45678. It will be recalled that the bill has been tabulated to the first quantity column and that coil 111 is energized to close contacts 111a (Fig. 21a). When key 10-1 is now operated to type the digit 1 into the hundreds or first column of the quantity field, the key contacts 28 close, followed by closure of key contacts 28' and 28p. The closure of contacts 28 thus precedes the closure of contacts 28'. Referring now to Fig. 21a, the closure of contacts 28 of key 10-1, with contacts 111a in closed condition, establishes the following circuit:

40 *Coil 120 circuit.*—Line 101, normally closed contacts 117a, contacts 111a, connection b-6, common 118 of the key contacts, inner key contacts 28-1, common 119 of the key contacts, connection b-5, coil 120, line 102.

45 *Coil 120* closes contacts 120a to form the following circuit (Fig. 21a):

Switch SW-#1 stepping circuit.—Line 101, contacts 120a, in parallel through magnet SWM-1 and a coil 121, line 102.

50 *Energization of magnet SWM-1* steps the feeler of switch SW-1 to the "1" column segment 85, preparing the first or left hand column of the coils 114 for receiving the first quantity digit. The selection of a coil in this column is controlled by closure of outer key contacts 28' which occurs immediately after closure of contacts 28. Thus, it is made certain that the selection of the column of coils 114 by switch SW-1 to receive an entry takes place before the selection of a coil 114 in the selected column. It should be noted that even were contacts 28 and 28' to be closed simultaneously, the column selecting action of switch SW-#1 would precede the digit coil selecting action of the key contacts because of the stepping action of the switch being effected rapidly and being completed before the key coils 115 succeed in closing the 115a contacts.

55 As a result of the closing of key contacts 28'-1, the following circuit forms (Fig. 21a):

Key coil circuit.—Line 101, contacts 117a, 111a, connection b-6, common wire 118, contacts 28'-1, connection b-23, key coils 115-1, common wire 122, line 102.

60 Referring to Fig. 21c, coils 115-1 close the row

70 75

of eight contacts 115a-1, but with switch SW-#1 now in first column selecting position, the closure of contacts 115a-1 only in this first column is effective to form a main circuit through the coil 114-1 of this column, as follows (Fig. 21c):

Value coil main circuit.—Line 102, coil 114-1 of the first column, contacts 115a-1 in series therewith, common wire 123, the connected, normally closed space relay contacts 124a, contacts 125a, column reduction relay contacts 126a, position "1" of switch SW-#1, line 101.

A stick circuit for the energized coil 114-1 of the left hand column is formed by closure of contacts 114a-1 as follows (Fig. 21c):

Value coil stick circuit.—Line 102, coil 114-1, contacts 114a-1, common wire 127, coil 125, in parallel through cam contacts A3 and column shift relay contacts 128a-h, common wire 129, in parallel through cam contacts A10 and total entry relay contacts 130a, normally closed contacts 131a, 132a, connection b-33 (continue with Fig. 21a), the left, normally closed side of error key contacts EKa, connection b-34, line 101.

Coil 125, energized by the above circuit, opens contacts 125a, common to the main circuits of the left hand column of coils 114, to make certain that not more than one coil 114 will be energized in this column.

The successive typing and punching of the remaining digits of the quantity and price repeatedly closes the SWM-1 circuit to step the switch SW-#1 to the successive switch positions correlated with the different value retaining relay columns. The main circuit of a coil 114 in the second column differs from the previously traced main circuit of the first column in extending through contacts 133a and position "2" of switch SW-#1. The stick circuit of the second column is similar to the stick circuit traced above but extends through a coil 133 and in parallel through cam contacts A2 and column shift contacts 128a-t. The coil 133 opens contacts 133a to prevent energization of more than one coil 114 in the second column. The main circuit of the units quantity column extends through contacts 134a and position "3" of switch SW-#1, while its stick circuit extends through coil 134, functioning to the same effect as coil 125 in preventing energization of more than one relay coil in the same column, and through cam contacts A1 and parallel column shift contacts 128a-u. The main circuits of coils 114 of the fourth to eighth columns, inclusive, of the retaining relay bank are established by the typing of the price digits and respectively include contacts 135a, 136a, 137a, 138a, and RH_a, and positions "4," "5," "6," "7," and "8" of the switch SW-1. The last three columns do not include column reduction contacts 126a. All of the last five columns do not include any A cam contacts and column shift contacts as these are unnecessary for the price columns, the price being entered into the product bank during one accumulator cycle, as will be explained later. The stick circuits of the fourth to seventh column coils 114 also include coils 135, 136, 137, and 138, functioning to the same effect as coil 125 of the first column stick circuit in opening the main circuits to prevent more than one coil in a column being energized during the typing of the item. The stick circuit of the right hand or eighth column of coils 114 includes a multi-contact relay magnet RH and a relay coil 139, energization of both of which determines that the last digit of the price or mul-

tiplicand factor has been set up and that multiplication may begin. Magnet RH opens contacts RH_a in the main circuit of the last column to prevent energization of more than one value retaining coil in this column.

Energization of the coils 114 closes associated 114b contacts (see Fig. 21d). In the assumed example, the contacts 114b-1, 2, 3, 4, 5, 6, 7, and 8 of the first to eight columns are now closed, representing the quantity factor 123 and the price factor 45678. The closed 114b contacts control entry of these factors into the product bank ACC-P to be multiplied, in a manner which will be explained hereinafter.

15 *The control by the space bar.*—It is not desired to type a "0" in any of the dollars order columns of the bill, unless preceded by a significant digit, but to leave such columns blank and to space to the next column. This is done by 20 operation of space bar SP of the typewriter. The operation of the space bar causes switch SW-#1 to step along so as to maintain the switch positions in proper correlation to the columns of value coils 114 and the corresponding bill columns. The operation of the space bar also causes the contacts 124a in the main circuits of each 25 column of coils 114 to open in order to make certain that a coil 114 of any column corresponding to a bill column being left blank is not picked up or energized.

When the space bar SP is operated, its associated contacts 28-SP close, completing the following circuit (Fig. 21a):

Coil 140 circuit.—Line 101, contacts 117a, 33 111a, connection b-8, contacts 28-SP, connection b-7, coil 140, line 102.

Coil 140 closes contacts 140a to form a circuit through multicontact space magnet 124, as follows (Fig. 21a):

10 *Magnet 124 circuit.*—Line 101, contacts 140a, magnet 124, line 102.

To maintain magnet 124 energized after contacts 140a open, the magnet closes contacts 124b to form the following circuit (Fig. 21a):

45 *Magnet 124 stick circuit.*—Line 101, in parallel through normally closed contacts 120b and 121a, contacts 124b, magnet 124, line 102.

Magnet 124 opens contacts 124a (Fig. 21c) of the main circuit lines of the columns of the value 50 retainer relay bank to prevent energization of any of coils 114 during the spacing operation.

Energization of coil 140 by the coil 140 circuit also closes contacts 140b (Fig. 21a), which shunt contacts 120a of the switch SW-#1 stepping circuit, to cause energization of magnet SWM-1, as a result of which switch SW-#1 is stepped to the next position, just as when a digit key is operated. When magnet SWM-1 is energized, the coil 121, in parallel therewith, also is energized and opens contacts 121a in the magnet 124 stick circuit, but the parallel contacts 120b continue to hold this stick circuit closed until a digit key is operated for setting up the first significant digit. When a digit key is operated, the coil 120 circuit forms, and coil 120 closes contacts 120a to establish the magnet SWM-1 circuit for advancing the switch SW-#1 and also opens contacts 120b of the magnet 124 stick circuit. When the magnet SWM-1 circuit forms, parallel coil 121 is also energized, opening contacts 121a to cause a complete break in the stick circuit of magnet 124. Thus, contacts 121a time the deenergization of the space relay magnet 124 to prevent reclosing 70 of contacts 124a of the main circuit lines of the

value coils 114 (Fig. 21c) until the switch SW-1 has been stepped to the position for selecting the value retaining column corresponding to the bill column in which the first digit is being typed.

It is desired to punch zeros in the card columns for spacing operations of corresponding columns of the bill sheet. For this reason, the space key contacts 28p (Fig. 21g) close whenever the space key is operated. The space key contacts 28p are in parallel with the zero key contacts 28p and, with the contacts PMa closed, cause operation of the zero punch key magnet 322-0 to cause punching of a zero.

Maintaining action of coil 111 during typing of price.—When the third or units order quantity column is typed, a coil 114 in the corresponding third column from the left of the value retaining bank is energized and held by its stick circuit. Common to the stick circuits of the column is the coil 134 (Fig. 21c) which, in addition to opening contacts 134a in the main circuit to prevent more than one coil 114 of the column being picked up, also closes contacts 134b in series with contacts 111b of coil 111 (see Fig. 21e). At this time, switch SW-#3 is still in quantity field position "2" (Fig. 21f), so that coil 110 is energized to hold contacts 110a closed, with the result that the coil 111 circuit #1 is still in effect, and coil 111 is now holding contacts 111b closed. Now, when contacts 134b close, the following circuit forms (Fig. 21e):

Coil 111 circuit #2.—Line 102, coil 111, contacts 111b, 134b, 142a, 143a, RHb, line 101.

After the units order quantity digit is punched and typed, the operator actuates the tab key to tabulate the first column of the price section of the bill to typing position. The operation of the tab key forms the switch SW-#3 stepping magnet circuit, bringing the switch SW-#3 to position "3" (Fig. 21f) which is not connected to any of sockets 105. When the switch left position "2", coil 110 was deenergized and contacts 110a opened to break the coil 111 circuit #1. The energization of coil 111 is maintained, however, through the coil 111 circuit #2 formed as a result of the previous entry of the units order quantity digit. Consequently, contacts 111a remain closed during the typing in the price columns of the bill, so as to cause punching of the price designations and to enable the last five columns of the value retaining bank to be set up in accordance with the price factor.

As a result of the typing of the cents units order or right hand digit of the price, the stick circuit of a corresponding digit value coil 114 in the right hand column of the value retaining bank is established. As stated before, this stick circuit includes coil 139 and the multi-contact relay magnet RH (see Fig. 21c).

Magnet RH opens contacts RHb in the coil 111 circuit #2, and coil 111 is now deenergized. When the operator, after typing the right hand price digit, tabulates the description field to typing position, switch SW-3 is stepped to position "5" (see Fig. 21f), the connected socket 103-5 of which is not plugged to any of sockets 105. Now, with coil 111 deenergized and contacts 111a open, the typing of any digits in the description field will not cause entry of the digits into the calculator unit.

Restoration of switch SW-#1.—The entry of the units order digit into the right hand column of the value retaining bank causes energization of magnet RH and coil 139. As explained above, magnet RH opens contacts RHb to break the

second circuit of coil 111, resulting in deenergization of the coil and opening of contacts 111a. The magnet RH also closes the right side of contacts RHc (bottom of Fig. 21b) to cause the switch SW-#1 to be restored to initial condition. This switch, having performed the function of correlating the columns of the value retaining bank to the corresponding columns of the quantity and price sections, may be restored to home position after the right hand price digit has been entered. As will be explained hereinafter, the product of the quantity and price is typed automatically into either the amount or credit sections of the bill, and this typing is required to enter the product into the value retaining bank. The restoration of the switch SW-#1 to home position prepares the switch for correlating the columns of the value retaining bank to the columns of the debit or credit section during the typing of the product in either one of these sections. The restoration of the switch SW-#1 occurs as a result of energization of magnet RH, which closes the right side of contacts RHc to establish the following circuit (Fig. 21b):

Switch SW-#1 release magnet.—Line 101, the right side of contacts RHc, selector switch contacts SWa-1 (closed as soon as the feeler leaves home position), magnet SWR-1, line 102.

Energization of magnet SWR-1 restores the feeler of switch SW-#1 to home position.

Concomitantly with typing of the last digit of the price, the corresponding digit perforation is punched in column 14 of the card W. As explained before, pattern card P (Fig. 11) is punched with account data in columns 15 through 32 and operation of the punch now takes place under control of card P to duplicate the account data in columns 15 through 32 of the work card. Thus, upon sensing of a perforation in the pattern card by a brush 321, the following circuit is established (Fig. 21g):

Duplicator circuit.—Line side 453, now-closed card lever relay contacts 457a, floating cam contacts 370, contact roll 320, a brush 321, a key magnet 322, and through resistance to line side 452.

Magnet 322 operates its related key 324 to cause punching of a duplicate perforation in the work card. In this manner, the card W is punched in columns 15 through 32 with the pattern card account data.

MULTIPLICATION

Magnet RH, energized as a result of entry of the last price digit, initiates multiplying operation, the quantity entry being treated as the multiplier and the price entry as the multiplicand. The multiplication is by the repeated addition method and requires performance of accumulator cycles by the product bank; hence the clutch magnet 40 (Figs. 1 and 5) must first be energized. When magnet RH was energized, it closed contacts RHd, forming the following circuit (Fig. 21f):

Clutch circuit #1.—Line 102, clutch magnet 40, wire 145, contacts RHd, line 101.

Energization of clutch magnet 40 initiates rotation of calculator shaft 36 (Figs. 1, 6, and 7) to perform accumulator and readout cycles (Figs. 20a and 20b). As previously explained, a series of three successive accumulator cycles accompanies each readout cycle. Hereinafter, the time of operation of R cam contacts may not only be referred to the portion of the readout cycle when the operation occurs but also to the accu-

mulator cycle which accompanies this portion of the readout cycle. Similarly the time of operation of A cam contacts may be referred to the accompanying portion of the readout cycle.

During the first accumulator cycle, cam contacts R9 (Fig. 20b) close, and when A9 cam contacts (Fig. 20a) also close at the "15" point, the following clutch circuit forms (Fig. 21f):

Clutch shunt circuit.—Line 102, magnet 40, contacts R9, contacts A9, line 101.

Cam contacts R9 remain closed during the second accumulator cycle, so that the clutch shunt circuit repeats, maintaining the clutch engaged for the third cycle, independently of clutch circuit #1. During the third accumulator cycle, the contacts R9 are open when cam contacts A9 close at the "15" point, and the continuation of the clutch engagement for the next accumulator cycle then depends on clutch circuit #1, requiring the contacts RHd to be closed. Assuming the multiplication is completed during the third cycle, the magnet RH is deenergized when cam contacts A5 make, as will be brought out later and, therefore, contacts RHd open and the clutch is disengaged at the D point of the third accumulator cycle. If multiplication is not completed during the third accumulator cycle of the first series, then clutch circuit #1 continues in effect and a fourth accumulator cycle or the first of a second series starts. During the latter cycle, cam contacts R9 make again and the clutch shunt circuit takes effect to cause the second and third accumulator cycles of the second series to be performed. Thus, if multiplication is not completed during a series of three accumulator cycles coextensive with a readout cycle, the calculator unit performs a complete new series of accumulator cycles. When multiplication is completed during any series, the clutch shunt circuit continues calculator shaft 36 in operation to the end of the series. Thus, the disengagement of the clutch can occur only at the end of a series of three accumulator cycles or the coextensive readout cycle.

Entry of multiplier into product bank.—The multiplication by the product bank is by the over and over addition method, involving entry of the units, tens, and hundreds orders of the multiplier (quantity) in succession. This successive entry of the orders of the multiplier is controlled by successive energization of column shift magnets 128—u, 128—t, and 128—h (Fig. 21e), of which the respective contacts 128a—u, t, and h are in the stick circuits of the third, second, and first columns of the value retaining coils 114 (Fig. 21c), which have received the quantity factor or multiplier. The energization of magnets 128u, t, and h in succession is controlled by the selector switch SW—#2, the feeler of which is advanced one position upon each agreement between the reading of the cycling counter, comprising column 10 (the left hand or highest order) of the product bank, with the reading of column 9 which receives the units, tens, and hundreds multiplier digits in successions. Initially, the columns of the product bank are at zero and, consequently, the brushes 51 of the ninth and tenth orders, or columns 9 and 10 of the product bank readout commutator PRO, are on common zero segment 53—0, as indicated in Fig. 21e.

It will be recalled that magnet RH and coil 139 were energized as a result of the entry into the right hand column of the value retaining means of the cents units price digit. Magnet

RH closed contacts RHd to establish clutch magnet circuit #1, traced above, to initiate accumulator cycles. Magnet RH also closed contacts RHe, and when cam contacts A5 close at the "14" point of the first accumulator cycle (see Fig. 20a), the following circuit forms (Fig. 21e):

Switch SW—#2 stepping circuit.—Line 102, stepping magnet SWM—2, collector ring 52 of column 10 of the product readout commutator PRO, the column 10 brush 51, segment 53—0, brush 51 of the ninth column, column 9 collector ring 52, contacts RHe, normally closed relay contacts 148a, 149a, 150a, cam contacts A5, line 101.

Magnet SWM—2 now advances the feeler of switch SW—#2 from home position to position "1". When this happens, the following circuit forms (Fig. 21e):

Magnet 128—u circuit.—Line 102, magnet 128—u, a relay coil 151—u, contacts 153a—u, contacts 134b (closed by energized coil 134 of the stick circuit of the third or units quantity order column of the value retaining bank), the "1" position of switch SW—#2, contacts 153a, line 101.

Coil 151—u closes stick contacts 151a—u to form a holding circuit for magnet 128—u and coil 151—u, maintained until the switch SW—#2 is advanced to position "2".

Magnet 128—u stick circuit.—Line 102, magnet 128—u, coil 151—u, contacts 151a—u, the "1" position of switch SW—#2, contacts 153a, line 101.

Magnet 128—u opens contacts 128a—u in the stick circuit of the energized value coil 114 of the units order quantity column of the value retaining bank, but this stick circuit remains closed through cam contacts A1, in parallel with contacts 128a—u, until after the entry period "9" through "1" of the second accumulator cycle.

Thus, during the first accumulator cycle, initiated by closure of contacts RHd to form clutch magnet circuit #1, magnet 128—u and coil 151—u have been energized. The energization of magnet 128—u and coil 151—u was timed by closure of cam contacts A5 to occur at the "14" point of the first accumulator cycle. Magnet 128—u closes the group of five contacts 128b—u (Fig. 21d) each connected to one of the entry magnets CM of columns 1 to 5 (units to tens of thousands orders) of the product bank, thereby preparing these columns to receive the five digits of the multiplicand. Magnet 128—u also closes contacts 128c—u connected to magnet CM of column 9 of the product bank, preparing this column to receive the units order digit of the multiplier. Coil 151—u closes contacts 151b—u connected to magnet CM of column 10 of the product bank, preparing this column to receive a cycle counting impulse. The above operations all take place during the first accumulator cycle following the closure of cam contacts A5 at "14". The entry of debit values into the product bank is timed by the plus emitter E+ (Figs. 1 and 21d), the brush 77 of which is now on an insulating segment of the emitter ring. Thus, entry of the values into the product bank does not occur during the first accumulator cycle, but is deferred until the second accumulator cycle.

In series with the feeler of the plus emitter E+ is a pair of contacts 154a, closed except when a credit entry is being made. Contacts 154a are closed by energization of coil 154 which occurs as soon as switch SW—L (Fig. 21a) is closed to

place current on the opposite lines 101 and 102. The circuit for coil 154 follows (Fig. 21f):

Coil 154 circuit.—Line 102, coil 154, credit relay contacts 155a, line 101.

Coil 154 remains energized to hold contacts 154a closed except when a credit entry is being made, during which time contacts 155a open, as will be brought out further on.

Entry of factors.—The multiplier and multiplicand are now represented by the closed 114b contacts (Fig. 21d) of the value retainer bank. Since the positions of the contacts 114b along their columns correspond to different values, the representation thereby of values may be considered as a positional value setting or representation. This positional representation is converted by the emitters E+ or E- into differentially timed equivalents for entry into the columns of the product bank. During the second accumulator cycle, which may be considered as the first multiplying cycle, the units order value of the multiplier is entered into column 9 of the product bank, the multiplicand is entered into columns 1 to 5, and column 10 is advanced one unit step as an indication of the performance of one multiplying cycle.

In the assumed example of a multiplier of 123, the units order value is "3" and contacts 114b-3 of the third column from the left of the bank of 114b contacts are closed. When the feeler of emitter E+ reaches position "3" during the first multiplying cycle, the following circuit is established (Fig. 21d):

Multiplier entry circuit.—Line 101, make and break contacts 75 (see also Fig. 20a), contacts 154a (now closed), the feeler 77 of emitter E+, the "3" segment of the emitter, common wire 156 of the row of 114b-3 contacts, the now closed 114b-3 contacts of the third column from the left, the common 157 of the latter column, the right, normally closed, side of a pair of contacts 130b of the total entry multi-contact relay magnet 130, the now closed 128c-u contacts, magnet CM of column 9 of the product bank, the common 158 of magnets CM, line 102.

Energization of this magnet CM at the "3" point of the cycle causes entry of the value "3" into column 9 of the product bank, as a result of which its readout brush 51 is advanced to commutator segment 53-3 (see Fig. 21e).

The entry circuits of the multiplicand are similar to the above entry circuit, except that they are routed through the 128b-u contacts, now closed by energized column shift magnet 128-u, into columns 1 to 5 of the product bank. Thus, by the end of the entry period of the second accumulator cycle, the multiplicand factor is standing in the five lowest order columns, or columns 1 to 5 of the product bank.

At the "1" point of the first multiplying cycle, an entry circuit is formed through magnet CM of column 10 of the product bank to advance the latter column one step as a count of the cycle of multiplication which has taken place. The entry circuit of column 10 is as follows (Fig. 21d):

Cycle counting entry circuit.—Line 101, contacts 75, 154a, position "1" of emitter E+, the common side of the "1" row of 114b contacts, line 159, contacts 151b-u (closed by now-energized coil 151-u), magnet CM of column 10, common 158, line 102.

The energization of this magnet CM causes the readout brush of column 10 to advance to segment 53-1 (see Fig. 21e).

Thus, at the end of the entry period of the first multiplying cycle, columns 1 to 5 of the product bank contain the multiplicand, column 9 contains the units order digit of the multiplier, and column 10 reads "1".

The units order digit of the multiplier, having been entered into column 9 of the product bank, the set up of the units order or third value retainer column from the left must be cleared. When magnet 128-u was energized at the "14" point of the first accumulator cycle, it opened contacts 128a-u in the stick circuit of the latter column, but the stick circuit was maintained through cam contacts A1 which were then closed and which do not open till the end of the entry period of the first multiplying cycle (Fig. 20a). Upon the opening of cam contacts A1, the stick circuit of the units order multiplier column of coils 114 breaks and the closed 114b contacts of the column open. Thus, after the units order multiplier digit has been entered once in column 9 of the product bank, further entry of this units digit is prevented, and column 9 remains set at the reading of the units order value of the multiplier, which, in the assumed example, is "3".

The number of multiplying cycles performed to multiply the multiplicand by the units order digit of the multiplier depends on the number of cycles which are required to bring cycle counting column 10 of the product bank into agreement with column 9. In the present example, three multiplying cycles occur before column 10 is advanced to "3", which matches the reading "3" in column 9. During each of the three multiplying cycles, the multiplicand is entered into columns 1 to 5 of the product bank, and column 10 is advanced one step. At the end of the entry period of the three multiplying cycles, the multiplicand has been multiplied by "3" (the units order multiplier digit), and column 10 stands at "3".

During the first multiplying cycle, when cam contacts A1 opened, the stick circuit of the units order multiplier column of the value retaining bank was broken, as explained before. As a result, coil 134 was deenergized, causing contacts 134b of the magnet 128-u main circuit to open. The magnet 128-u remains energized, however, through the magnet 128-u stick circuit which does not break until switch SW-#2 leaves position "1".

At the end of the entry period of the third multiplying cycle, the column 10 brush 51 of the commutator PRO is on segment "3" which is also engaged by the brush 51 of column 9. When cam contacts A5 close at "14" of the third multiplying cycle, the switch SW-#2 stepping circuit is again formed, the circuit extending this time through common segment "3" of columns 9 and 10. This circuit advances the switch SW-#2 to position "2". As a result of the switch leaving position "1", the stick circuit of magnet 128-u and coil 151-u (Fig. 21e) is broken, and contacts 128b-u, 128c-u, and 151b-u (Fig. 21d) open.

When switch SW-#2 reaches position "2", the circuit of column shift magnet 128-t is established (Fig. 21e):

Magnet 128-t circuit.—Line 102, magnet 128-t, coil 151-t, contacts 152a-t, contacts 133b, position "2" of switch SW-#2, contacts 153a, line 101.

Contacts 133b in the above circuit have been closed by energization of coil 133 in the stick circuit of the second value retainer column from

the left, which contains the tens order digit of the multiplier.

The closure of contacts 151a-t forms the stick circuit of magnet 128-t and coil 151-t, which remains in effect until switch SW-#2 leaves position "2".

Coil 151-t closes contacts 151b-t (Fig. 21d) which shunt contacts 151b-u and replace the latter in forming the cycle counting entry circuit.

Magnet 128-t opens contacts 128a-t (Fig. 21c) in the stick circuit of the second value coil column from the left. The stick circuit of the energized coil 114-2 in the latter column remains made through camera contacts A2. Magnet 128-t closes contacts 128c-t to connect the tens order multiplier column of contacts 114b (the second from the left, Fig. 21d) to column 9 of the product bank. Magnet 128-t also closes the groups of five 128-t contacts to connect the five multiplicand columns of contacts 114b to columns 2 to 6 of the product bank, thus shifting the entry circuit of each order of the multiplicand to the next higher order of the product bank, equivalent to multiplying the multiplicand by ten. Thus, as a consequence of switch SW-#2 advancing to position "2", the control of the column 10 of the product bank is shifted to contacts 151b-t (Fig. 21d). The entry circuit of column 9 is shifted, through contacts 128c-t to the tens order multiplier column of contacts 114b, and the entry circuits of the multiplicand are shifted, through the group of contacts 128b-t to columns 2 to 6 of the product bank. All of this occurred as a result of the matching of the readings of columns 9 and 10 of the product bank during the third multiplying cycle, which is the fourth accumulator cycle of the series initiated by completion of the entry of the last multiplicand digit in the right hand column of the value retaining bank. During the next cycle or the fourth multiplying cycle, the cycle counting entry circuit adds "1" to the previous "3" reading of column 10 of the product bank, the multiplier entry circuit adds "2" (the tens order digit of the multiplier), represented by the second column 114b contacts from the left, to the column 9 reading of "3", and the multiplicand is entered in columns 2 to 6 of the product bank. At the end of the entry period of the fourth multiplying cycle, cam contacts A2 (Fig. 20a) open, breaking the stick circuit of the tens order multiplier column of coils 114 (Fig. 21c), causing contacts 114b-2 (Fig. 21d) to open, to prevent more than one cycle of entry of the tens order multiplier digit into column 9 of the product bank. When the stick circuit of the tens order multiplier column of coils 114 is broken, the common coil 133 is deenergized, opening contacts 133b in the main circuit of magnet 128-t. The stick circuit of magnet 128-t and connected coil 151-t maintains these two energized until switch SW-#2 leaves position "2".

During the fifth multiplying cycle, the multiplicand is again entered into columns 2 to 6 of the product bank and column 10 is advanced one step, bringing its reading to "5" which matches the reading "5" of column 9. When cam contacts A5 make during this cycle, the switch SW-#2 stepping circuit is again formed, advancing switch SW-#2 to position "3" (Fig. 21e). As a result, magnet 128-t and coil 151-t are deenergized, and the main circuit of magnet 128-h and coil 151-h made through contacts 152a-h, contacts 125b, and position "3" of switch 75

SW-#2. The closure of contacts 151a-h form the stick circuit of magnet 128-h and coil 151-h, which remains in effect till switch SW-#2 leaves position "3". Coil 151-h closes contacts 151b-h which are in parallel with contacts 151b-u and 151b-t and replace the latter in forming the cycle counting entry circuit. Coil 128-h opens contacts 128a-h in the stick circuit of the left hand or units order multiplier column of value retaining coils 114, leaving the stick circuit made through cam contacts A3. Magnet 128-h also closes contacts 128c-h (Fig. 21d) to connect the left hand column of 114b contacts to column 9 of the product bank. Magnet 128-h also closes the group of five 128b-h contacts to connect the five right hand columns of contacts 114b, set up in accordance with the multiplicand, to columns 3 to 1 of the product bank, thus shifting the entry circuit of each order of the multiplicand to the next higher order of the product bank.

During the next accumulator cycle, which is the sixth multiplier cycle, "1" is added to column 10 of the product bank, "1" (the hundreds order multiplier digit in the assumed example) is added to column 9, and the multiplicand is entered into columns 3 to 7 of the product bank. When cam contacts A3 open during the sixth multiplier cycle, the stick circuit of the left hand column of coils 114 is broken and coil 125 therein is deenergized, breaking the main circuit of magnet 128-h and coil 151-h. During this same cycle, the reading of columns 9 and 10 of the product bank match and when cam contacts A5 close, the circuit of switch SW-#2 is again made and the switch advances to position "4", causing deenergization of magnet 128-h and coil 151-h.

It is to be noted that the multiplication of the two factors is by the over and over addition method, with the multiplicand entry shifted to the next high orders of the product bank for each shift to the next higher order of the multiplier. In the present case, when the hundreds order of the multiplier has multiplied the multiplicand, the multiplication operation is complete and the product bank contains the product of the two factors. Columns 1 to 7 of this bank directly receive the product, and if the product exceeds seven digits, the usual carry-over operations enter the eighth digit into column 8. Since, for the purposes of the disclosure, the number of digits in both factors is limited to a total of eight, the product cannot exceed eight digits, which is within the capacity of columns 1 to 8 of the product bank. Thus, at the end of the multiplication, columns 1 to 8 of the product bank and the corresponding columns of the readout commutator PRO represent the product.

It should be noted that the main circuits of column shift magnets 128-u, t, and h include, respectively, normally closed contacts 152a-u, t, and h. The contacts remain closed only if the coils 152-u, t, and h are not energized. Reference to Fig. 21c shows that these coils are in series with the zero coils 114-0 of the three left hand columns or the multiplier columns. If the setup of any of these columns is zero, then the coil 152 of the column is energized, opening the related 152a contacts of the column shift magnet circuit, preventing energization of the magnet 128 and coil 151 corresponding to the column in which the zero setup is made. Thus, if the units order multiplier quantity were "0", then coil 152-u would be energized, contacts 152a-u would be open, and the magnet 128-u circuit

would not form to energize magnet 128-u and coil 151-u. Consequently, contacts 151b-u would not close and the cycle counting entry circuit to enter "1" into column 10 of the product bank would not be established during the first multiplying cycle. Column 9 would also remain at zero. Nor would the group of contacts 128b-u close, so that the multiplicand would not be entered into columns 1 to 5 of the product bank. When cam contacts A5 closed during this first multiplying cycle, switch SW-#2 would be advanced to position "2".

If, instead of entering "0" into any multiplier column of the value retaining bank, the operator had depressed the space bar to space to the next column, the main and stick circuits for coils 114 of the column for which the space bar had been operated would not form. Consequently, the coil 128, if the hundreds order multiplier column had been skipped; or the coil 133, if the tens order multiplier column had been skipped; or the coil 134, if the units order multiplier column had been skipped, would not be energized and their corresponding 125b, 133b, and 134b contacts would not be closed. With contacts 125b open, the main circuit of magnet 128-h and coil 151-h cannot form through position "3" of switch SW-#2; with contacts 133b open, the main circuit of magnet 128-t and coil 151-t cannot form through position "2" of the switch; and with contacts 134b open, the circuits of magnet 128-u and coil 151-u cannot be made through position "1" of the switch. Thus, if a space bar operation has been effected for any of the multiplier columns of the value retainer bank, the entry of the multiplicand and the advance of column 10 of the product bank cannot take place, and the switch SW-#2 is stepped along to the next position.

Thus, when either a zero set up in a multiplier column of the value retaining bank has been made or the column has been skipped by a space bar operation, the column shift magnet 128 and coil 151 corresponding to the multiplier column are not energized, and switch SW-#2 advances to the next position.

Restoration of switch SW-#2.—During the last multiplying cycle, when columns 9 and 10 of the product bank matched, switch SW-#2 was advanced to position "4". When this occurs, the following circuit forms (Fig. 21e):

Release magnet SWR-2.—Line 102, in parallel through magnet SWR-2 and coils 153 and 131, segment 85-4 of switch SW-#2, feeler 86, the common 84, contacts 153a, line 101.

Coil 153 immediately opens contacts 153a to eliminate any possibility of the formation of a magnet 128 (and coil 151) circuit upon the wiping of the switch segment by feeler 86 as it returns to home position. Simultaneously with the opening of contacts 153a, contacts 153b are closed. With the feeler of switch SW-#2 still away from home position, contacts SWa-2 (Fig. 2) of this switch are closed and with contacts 153b also closed, the following stick circuit for magnet SWR-2 and coils 131 and 153 is formed (Fig. 21e):

SWR-2 stick circuit.—Line 102, in parallel through magnet SWR-2 and coils 131 and 153, contacts 153b, contacts SWa-2, line 101.

When the switch feeler reaches home position, contacts SWa-2 open, breaking the above stick circuit.

When coil 131 is energized, it opens contacts 131a in the common return line of the stick cir-

cuits of the value coils 114 (see Fig. 21c). As a result, the setting of the five right-hand or multiplicand columns of the value retainer bank is cleared. The three left-hand or multiplier columns already were cleared during the multiplying cycles, due to successive opening of the 128a contacts and their companion A1, A2 and A3 cam contacts.

When multiplication is completed, coil 131 is energized, as explained above, and contacts 131a open to break the stick circuits of value coils 114, causing deenergization of magnet RH. Contacts RHe in the switch SW-#2 stepping circuit open, preventing advance of switch SW-#2 from its home position to which it has been restored.

Also, contacts RHD (Fig. 21f) open, breaking clutch circuit #1. If this occurs during the first or second accumulator cycle of a series, the calculator shaft continues in operation, because of the clutch shunt circuit, to the end of the third accumulator cycle of the series, as explained before. If the multiplication is completed during the third accumulator cycle of the series, the breaking of clutch circuit #1 causes the calculator unit to stop at the end of the series.

AUTO TYPING OF PRODUCT

The auto typing of the debit product requires three precedent conditions; one, completion of multiplication; two, the arrival of the amount section of the bill at typing position as a result of a tab key operation following typing of the description, and three, the arrival of the first column 33 of the amount field of the card W at punching position. Similarly, auto typing of a computed credit or credit product requires completion of multiplication, the tabular spacing of the credit section of the bill to typing position, and the arrival of column 33 of the card at punching position. For the present, the auto typing of a debit product only will be considered.

The satisfying of the three conditions for read out of a debit product causes a circuit to form through coils 149 and 161 (Fig. 21e). In order to make clear the requirements for completing the circuit of coils 149 and 161, their pickup circuit is traced below (see Fig. 21e):

Coils 149 and 161 circuit.—Line 102, coils 149 and 161, contacts 160a, contacts 163a, contacts 162a, relay contacts 465a, cam contacts R2, line 101.

Contacts 160a are closed only when multiplication is completed, in a manner which will be explained later. Contacts 163a do not open except when dealing with a credit product. Contacts 162a close when the debit section of the bill is tabulated to typing position and in accordance with the timing imposed by cam contacts R12 (Fig. 20b). Contacts 465a close only when column 33 of card W reaches punching position. Cam contacts R2 close briefly near the end of the first accumulator cycle of a series of three coextensive with a readout cycle. Thus, if multiplication is completed, and the debit section of the bill and the amount field of the card brought to their respective recording positions during the second or third accumulator cycle of a series coextensive with a readout cycle, the open condition of cam contacts R2 prevents the completion of the coils 149 and 161 circuit, and read out cannot begin till the next read out cycle.

The closing of contacts 162a is dependent on the closure of cam contacts R12 (Fig. 20b) and on the switch SW-#3 being brought to position

"6" (see Fig. 21f) by a tabular spacing operation after the description has been typed. Cam contacts R12 open shortly after the "5" point of the first accumulator cycle of a series coextensive with a readout cycle begins. Thus, if the switch SW—#3 is brought to switch position "6" before the "5" point of the first accumulator cycle and contacts 465a also have closed, and if contacts 160a also close during the same accumulator cycle as a result of completion of multiplication, then the coils 149 and 161 circuit is established, causing read out of the product to begin at column "8" point of the readout cycle. If, however, the switch SW—#3 is brought to position "6" after cam contacts R12 open during the first accumulator cycle of a series coextensive with a readout cycle, then the reclosing of contacts R12 does not occur till the next accumulator cycle and after cam contacts R2 open. Thus, although contacts 162a will be closed during the latter readout cycle, the cam contacts R2 will be open and the coils 149 and 161 circuit will not be completed, so that read out will not occur during this read out cycle but will be deferred until the next readout cycle occurs and at a time controlled by closure of cam contacts R2 in the latter cycle.

In above manner, the cam contacts R12 prevent read out of a debit from beginning at the "8" column point of a readout cycle if the multiplication has been completed during the first accumulator cycle and the tab key has not been depressed before the "5" point of the latter accumulator cycle, and read out is deferred to the next readout cycle. Further, unless card column 33 is in punching position, contacts 465a are open and read out is deferred. In this manner, read out will not begin before sufficient time has elapsed for the debit section of the bill and the amount field of the card to reach their respective recording positions.

The closing of contacts 160a in the coils 149 and 161 circuit as a result of completion of multiplication is effected when coil 131 is energized by the release magnet SWR—2 circuit. Coil 131 closes contacts 131b to form the following circuit (Fig. 21e):

Coil 160 circuit.—Line 102, coil 160, contacts 131b, line 101.

Coil 160 closes contacts 160b to form a stick circuit extending through product bank reset contacts RMa—P (also see Fig. 1) which do not open until resetting of the product bank occurs after the read out of the product value.

The closing of contacts 162a in the coils 149 and 161 circuit is effected by energization of coil 162. During typing of the description, switch SW—#3 is in position "5" and operation of the tab key after the description is completed brings the switch to position "6." The circuit for coil 162 is then completed during the closed period of cam contacts R12, as follows (Fig. 21f):

Coil 162 circuit.—Line 101, position "6" of switch SW—#3, socket 103—6, connection 104 to socket 105—3, contacts R12, coil 162, line 102.

Coil 162 closes contacts 162b, shunting cam contacts R12, and closes contacts 162a in the coils 149 and 161 circuit.

Contacts 465a are closed when the first column 33 of the amount section of the card W is in punching position. For this purpose, a plug connection is made between column 33 commutator contact 424 (see Figs. 11 and 21g) and a plug hub 466. Contact 424 of column 33 is also plugged to a plug hub 467 for a purpose which

will be made clear hereinafter. When card column 33 reaches punching position, a commutator brush 422 engages column 33, contact 424, closing the following circuit (Fig. 21g):

Coils 465 and 462 circuit.—Line 102, in parallel through coils 465 and 468, plug hubs 466 and 467, the plug wires to contact 424 of column 33, brush 422, brush 423, common 425, post p8, post p7, floating cam contacts 370, card lever relay contacts 457a, latch contacts 403, to punch line side 453.

Coil 465 closes contacts 465a (Fig. 21e) in the coils 149 and 161 circuit.

Upon formation of the coils 149 and 161 circuit by completion of multiplication, tabulating of the debit section of the bill to typing position, and arrival of column 33 of the card at punching position, coil 161 closes contacts 161a to provide a stick circuit through cam contacts R1. It may be noted that when the punch unit is not to be operated together with the typewriter and calculator, contacts 465a are shunted out by switch blade #2 (Fig. 21a), which in "off" position bridges connections b—75 and b—76.

Readout cycles.—Coil 162 also closes contacts 162c to form the following clutch magnet circuit (Fig. 21f):

Clutch circuit #2.—Line 102, magnet 40, wire 145, contacts 163b, contacts 162c, contacts 160c (closed by energization of coil 160 at the end of the multiplication operation), cam contacts A9, line 101.

If multiplication is completed during any of the three accumulator cycles of a series and coil 162 is energized meanwhile, the above clutch circuit will continue the calculator shaft in operation for the next series of three accumulator cycles. If the coil 162 is not energized during a series of three cycles in which multiplication is completed, the above clutch circuit does not form, and continuation of the clutch operation awaits tabular spacing of the debit section to typing position with consequent energization of coil 162. Thus, if the multiplication is completed during any of the three accumulator cycles of a series and magnet 162 has not been energized, the magnet RH, deenergized by completion of multiplication, permits contacts RHd to open and break clutch circuit #1, but the clutch shunt circuit causes the accumulator cycles to continue until the series is completed. The calculator shaft 36 then stops. Subsequently, upon energization of magnet 162 and closure of contacts 162c, clutch circuit #2 is formed, and the shaft 36 resumes operation.

Independently of contacts 162c, the clutch magnet will be energized if multiplication has been completed and coils 162 and 465 energized during the first accumulator cycle of a series. In that event, the coils 149 and 161 circuit forms and coil 149 closes contacts 149c to form the following circuit (Fig. 21f):

Coil 148 circuit.—Line 102, coil 148, contacts 149c, line 101.

Coil 148 closes contacts 148b to provide a stick circuit timed by cam contacts A11.

Coil 148 also closes contacts 148c in parallel with contacts 162c to form the circuit of clutch magnet 40.

If the multiplication is completed during the second or third accumulator cycle of a series, cam contacts R2 will not be closed and the coils 149 and 161 circuit not yet completed. The continuation of the operation of the calculator shaft 36 then is effected by the closure of contacts 162c

to form clutch circuit #2. During the first accumulator cycle of the next series, with all the precedent conditions satisfied, when contacts R2 close, and coils 149 and 161 circuit will be established, in turn forming the coil 148 circuit, contacts 148c of which provide a clutch magnet circuit parallel to clutch circuit #2.

Clutch circuit #2 through contacts 162c remains effective while switch SW-#3 is in position "6". At the Tab point of the first readout cycle, an automatic tabular spacing operation, explained fully later, occurs to bring switch SW-#3 to position "7" and the cents field of the amount section to typing position. At this point, the clutch circuit through contacts 162c opens, but the clutch circuit through contacts 148c remains made to carry the calculator unit into a second readout cycle. During the first accumulator cycle occurring within the second readout cycle, the clutch shunt circuit takes effect to continue the clutch in operation, regardless of opening of contacts 148c near the end of the latter accumulator cycle, to the end of the second readout cycle.

In above manner, the calculator unit is caused to perform two successive readout cycles during which read out of the debit product occurs. It may be stated at this point that two readout cycles are also provided for reading out a credit product, with contacts 171c (Fig. 21f) replacing contacts 162c in the formation of clutch circuit #2, and contacts 148c performing in the same manner as described above. Also, during the reading out of a total, the shaft 36 performs two successive readout cycles, with contacts 187b (Fig. 21f) shunting contacts 163b, 148c, 162c, and 160c, to form the clutch circuit through cam contacts A9, and contacts 186b shunting contacts 187b to function to the same effect as contacts 148c in causing operation of the shaft 36 to continue for two readout cycles.

Debit read out.—Coil 161 closes contacts 161b in the common side of the product auto type emitter circuits (see Fig. 21b).

Coil 149 opens contacts 149a in the switch SW-#2 stepping circuit (Fig. 21e). Contacts 148a in the latter circuit are opened by coil 148. As will be brought out later, the auto typing of the product results in the reclosure of contacts RHe in the latter circuit at the "1" point of the second readout cycle. But with the contacts 148a open, the switch SW-#2 stepping circuit does not form. Coil 148 is deenergized when cam contacts A11 open during the first accumulator cycle of the second readout cycle. This occurs after cam contacts A5 in the switch SW-#2 stepping circuit have opened, so that during this first accumulator cycle, the latter circuit cannot form. During the second, following accumulator cycle, contacts RHe reopen before cam contacts A5 make, as will be explained further hereinafter, and the circuit through magnet SWM-#2 cannot then form even though contacts 148a and 149a have since closed. The switch SW-#2 is thus prevented from advancing from home position during the readout cycles in which the product is auto typed.

Coil 149 also closed contacts 149b which are in parallel with contacts 110a (Fig. 21e) and replace the latter in forming the circuit of coil 111. 70 Coil 111 closes contacts 111a (Fig. 21a) to condition the calculator unit for entering the product, as it is auto typed, into the value retaining means. Coil 111 also closes contacts 111d (Fig. 21g) to establish the circuit of relay magnet PM 75

so that typing of the digits of the product in the debit section of the bill will cause concomitant punching of the digit designations in amount columns 33 to 40 of the work card W.

6 To recapitulate, the value retaining bank has been cleared, the product bank is carrying the debit product obtained by multiplying the value in the quantity columns of the bill by the value in the price columns, the calculator cycle shaft 10 36 is in operation, coil 160 (Fig. 21e) is energized, the first column of the debit section of the bill is in typing position, the first column (33) of the amount field of the card W is in punching position, coils 149 and 161 (Fig. 21e) are energized, contacts 161b in series with the feeler 80 of the product auto type emitter E-P (Fig. 21b) are closed, coil 111 (Fig. 21e) is energized and its contacts 111a and 111d closed (Fig. 21a), punch connecting relay magnet PM (Fig. 21g), and coils 148 and 162 (Fig. 21f) are all energized.

15 The auto read out of the product requires the closure of contacts 161b in series with the feeler of product emitter E-P (Fig. 21b). The closure of contacts 161b is effected by energization of coil 161 in the coils 149 and 161 circuit, the formation of which has been explained above. The coils and 161 circuit may be established during the first accumulator cycle of a series provided the switch SW-#3 is advanced to switch 20 position "6" before the "5" of the latter cycle and provided, further that multiplication is completed during this cycle. The auto read out will then begin at point "8" of the readout cycle in which the first accumulator cycle lies. If the 25 coils 149 and 161 circuit is not completed during the first accumulator cycle of a series, the auto read out begins at point "8" of the next readout cycle.

30 The "8", "7", "6" . . . "2", "1" segments of emitter E-P correspond to columns or orders of the product bank. Assuming that there is the significant value "3" in column 8 of the product bank, when the feeler of emitter E-P reaches spot "8", the following circuit forms (Fig. 21b):

35 *Product auto readout circuit.*—Line 101, make and break contacts 83, contacts 161b, feeler 80 of emitter E-P, spot "8" thereof, a pair of normally closed relay contacts 164a, the normally closed right side of a pair of relay points 165a-8, the collector ring of column 8 of the readout commutator PRO, the brush 51 engaged therewith, the segment 53-3 on which the brush is resting, wire 166-3, connection b-14 (continue with Fig. 21a) key solenoid 30-3 (also see Fig. 9), connection b-9, pickup relay coil 167, line 102.

40 Energization of solenoid 30-3 operates typewriter key 10-3 to print a "3" in the first or highest order column of the debit section of the bill.

45 Operation of digit key 10-3 closes its contacts 28p (Fig. 21g), which, in the manner described before, establishes a circuit through magnet 323-3 to cause punching of a 3 designation in column 33 of the card W.

50 Coil 167 is the pickup coil of a duo-wound magnet and its energization by the product auto readout circuit closes contacts 167a to form the following circuit through the companion holding coil 167' (Fig. 21a):

55 *Holding coil 167' circuit.*—Line 102, coil 167', contacts 167a, contacts 161c (coil 161 is now energized by the coils 149 and 161 circuit), line 101.

60 Coil 167' when energized, closes the normally open side of contacts 167b, wired through con-

nection $b-11$ to the zero solenoid $30-0$ (Fig. 21a), and opens the normally closed side, wired through connection $b-32$ to the space bar solenoid $30-SP$. Thus, the typing of a significant figure has connected one side of contacts $167b$ to the zero key solenoid and disconnected the other side from the space bar solenoid. The position of contacts $167b$ determines whether a zero readout of a dollars order column of the readout commutator should be routed to the zero key solenoid or to the space bar solenoid. If, for example, the highest order in column 8 of the product commutator PRO had been in zero position, the product readout circuit would be as follows (Fig. 21b):

Dollars order zero product readout.—Beginning as in the previous readout circuit and continuing from brush 51 of column 8 to the segment 53-0, line 166-0, wire 168 (continue with Fig. 21a), the center blade of contacts $167b$, the normally closed right side of these contacts, connection $b-32$, solenoid $30-SP$, common wire 169, connection $b-10$, line 102.

The energization of solenoid $30-SP$ operates the space bar to space the next column of the debit section of the bill to typing position. In this manner, the presence of zeros, in the dollars orders of the commutator PRO, which precede the first significant figure does not result in the typing of zeros but in space bar operations to space the corresponding columns of the dollars field of the debit section past the typing position. However, the operation of the space key closes its contacts $28p$ (Fig. 21g) which being in parallel with 0 key contacts $28p$, causes a zero designation to be punched in the card column. The presence of the first significant dollars digit in the commutator PRO causes energization of coils 167 and $167'$ and shifting of contacts $167b$ to disconnect these contacts from the space bar solenoid and to connect them, instead, to the "0" key solenoid. Thus, if column 8 has a significant figure, the left side of contacts $167b$ will be closed and a zero readout circuit from column 7 of the product bank will be routed through connection $b-11$ to the zero solenoid $30-0$. Thus, a zero will be typed in the second column of the amount section when a significant digit has been typed in the preceding or first column.

It is desired to print zeros in the cents columns of the amount section, whether or not preceded by a significant digit. Accordingly, the common zero segment 53-0 of the cents order columns, or columns 1 and 2 of the product bank, is not connected to the other zero segments, but is connected through a wire 170 (see Figs. 21b and 21a in order) directly to connection $b-11$ which leads to zero solenoid $30-0$. The condition of contacts $167b$ thus has no influence on the zero read out of the cents columns of the product bank, and if a zero occurs in a cents order of the product, even if not preceded by a significant digit, a zero will be typed in the corresponding cents order column of the amount section of the bill.

Automatic tabular spacing.—Between the units dollars order column of the amount section and the next or tens of cents column, it is usually desired to provide extra spacing, and this is done in the present case by an automatic tabular key operation controlled by the auto type emitter E-P. Of course, if the extra spacing between the dollars and cents fields should not be desired, then the automatic tabular spacing operation would be omitted. The automatic tabular spac-

ing operation is initiated by engagement of the feeler 80 of emitter E-P with a TAB spot which follows the "3" or units dollars order spot. The TAB spot is spaced from the following spot "2" twice the normal amount between successive spots in order to provide ample time for this tabular spacing operation to be completed before the read out of the tens of cents order of the product begins. The auto tab circuit is as follows (Fig. 21b):

Auto tab circuit.—Line 101, make and break contacts 83, contacts $161b$, the feeler 80 of emitter E-P, the TAB spot, connection $b-21$ (continue with Fig. 21a), solenoid $30-TAB$, wire 169, line 102.

Energization of solenoid $30-TAB$ effects operation of the tab key to tabular space the first cents column of the amount field of the bill to typing position.

The tens and units of cents values are then read out in succession.

Resetting of the product bank.—After passing the "1" spot of emitter E-P, corresponding to the units cents order, the feeler 80 engages a reset spot, causing the following circuit to form (Fig. 21b):

Product bank reset circuit.—Beginning as in the preceding readout circuits and proceeding from the feeler 80 through the reset spot, connection $b-51$ (continue with Fig. 21a), the full line position of product bank reset switch SW-PR, connection $b-50$ (return to Fig. 21b), reset magnet RM-P, line 102.

Energization of magnet RM-P causes zeroizing of the product bank. During the resetting operation, reset contacts RMa-P (see Fig. 1) are opened. The opening of these contacts breaks the stick circuit of coil 160 (Fig. 21e).

Automatic carriage return.—After the product has been typed on a line of the bill, the carriage return key solenoid $30-CR$ may be energized automatically to bring the beginning of the next line to typing position. If the punch is not being operated in conjunction with the typewriter and calculator, the gang switch S-SP is then in "off" position. A switch blade #5 of this gang switch is then in "off" position (see Fig. 21a, bottom right) and directly connecting the binding posts $b-68$ and $b-61$. Under this condition, the automatic carriage return occurs as the brush of emitter E-P wipes the reset spot, and results from the following circuit (Fig. 21b):

Automatic carriage return circuit.—Beginning as in the product bank reset circuit and continuing from connection $b-51$ (turn to Fig. 21a) through contacts $171a$ (normally closed) to connection $b-68$, switch blade #5 in "off" position, connection $b-61$, carriage return solenoid $30-CR$, connection $b-60$, to line 102.

Energization of solenoid $30-CR$ effects carriage return and accompanying line spacing of the bill sheet.

Assuming, instead, that the punch unit is being operated conjointly with the typewriter and calculator, gang switch SW-SP is in "on" position. With switch blade #5 (Fig. 21a) in "on" position, the carriage return solenoid is disconnected from the reset spot of the emitter. The carriage return then occurs upon closure of relay contacts $480a$ which connect the switch blade #5 in "on" position to line 101. The auto carriage return circuit is then from line 101 through contacts $480a$, binding post $b-61$, switch blade #5 in "on" position, connection $b-61$, solenoid $30-CR$, connection $b-60$, to line 102.

Contacts 480a close upon energization of a relay coil 480 (Fig. 21g). This occurs upon escape of the card carriage to the last column position. It will be recalled that skip bar 360 (Figs. 19 and 19a) has a high portion spanning columns 41 to 80. Thus, upon punching of column 40 with the last product digit, the skip bar raises skip lifter 361 to disengage pawl 350 from escapement rack 312. In the manner explained before, the card carriage therupon escapes to its last column eject position. As the carriage reaches eject position, its lug 372 acts through lever 373 to close last column contacts 374 (Fig. 19). Closure of contacts 374 caused energization of last column relay 455. Contacts 455a close to energize stacker or eject magnet 376. At the end of the eject operation, contacts 392 close, initiating a feed cycle, all as explained before. Closure of contacts 392 also establishes a circuit from line side 453 through contacts 392, 20 relay coil 480, to line 102. Coil 480 closes contacts 480a (Fig. 21a) as a result of which the auto carriage return circuit through switch blade #5, in "on" position, is completed, as explained previously. In this manner, it is made certain that a new line of the bill will not be brought into position to be typed until a cycle of operations has been initiated in the punch unit for ejecting the card punched with the previous line of information for feeding in a new card.

ENTRY OF PRODUCT INTO TOTAL BANK

The product is entered into the total bank which accumulates the debits and credits. All values typed into the debit or credit section of the bill are entered as a result of the typing thereof into the total bank.

Before auto typing of the product began, the coil 111 circuit was established through contacts 149b (Fig. 21e). Thus, contacts 111a (Fig. 21a) are closed during auto typing operation and the depression of the digit keys will result in the setting up of the value retainer bank (Figs. 21c and d) to represent the typed values, in the same manner as when the quantity and price values were typed. The entry of the right-hand or units of cents digit of the product into the right-hand column of the retainer bank causes energization of magnet RH. This occurs at the "1" point of the second effective readout cycle. At the following reset point, the product bank is reset, automatic carriage return takes place, and as a result of the opening of reset contacts RMa-P, the coil 160 circuit (Fig. 21e) is broken, all as explained before. When cam contacts R1 open during the second effective readout cycle, the stick circuit of coils 149 and 161 is broken. Consequently, contacts 149b in the coil 111 circuit (Fig. 21e) reopen to deenergize the latter coil; contacts 149a in the switch SW-#2 stepping circuit reclose, and contacts 161b in the common side of the product/auto type circuits open. When cam contacts A11 open during the first accumulator cycle lying within the second effective readout cycle, the stick circuit of coil 148 (Fig. 21f) breaks, and contacts 148a in the switch SW-#2 stepping circuit reclose. At this point, contacts RHe (Fig. 21e) in the latter circuit are closed because magnet RH is energized. But cam contacts A5 open before cam contacts A11 break so that contacts 148a are still open while cam contacts A5 are closed and, consequently, the switch SW-#2 stepping circuit does not form. During the next accumulator cycle,

the contacts RHe will open, as will be brought out further on, so that the latter circuit also does not form during the remainder of the second effective readout cycle.

5 Magnet RH is energized at the "1" column point of the second effective readout cycle, closing contacts RHf (top of Fig. 21f). After the entry period of the accompanying accumulator cycle, cam contacts A7 (Fig. 20a) close. At this point, coil 148 is still energized and contacts 148d are closed. With cam contacts A7, contacts RHf, and contacts 148d closed, a circuit is formed through total entry relay magnet 130 as follows (Fig. 21f, at top):

Total entry relay magnet.—Line 102, magnet 130, contacts RHf, 148d, cam contacts A7, line 101.

Magnet 130 closes contacts 130c to form a stick circuit for the magnet, extending through cam contacts A6 which do not open until after the entry period of the following accumulator cycle.

20 Energization of magnet 130 closes the left, normally open sides of the 130b group of contacts (see Fig. 21d) and opens the normally closed sides. The opening of the latter sides disconnects the columns of contacts 114b of the value retainer bank from the product bank columns, while the closing of the left sides of contacts 130b connects the columns of 114b contacts to the columns of the total bank, ACC-T. All this occurs during the first accumulator cycle of the series coextensive with the second effective readout cycle. During the next accumulator cycle, the setting of the bank of 114b contacts, representing the automatically typed debit product, is converted into entries of the product into the total bank. Assuming, for instance, that the highest order, or the first column from the left, of the value retainer bank is set to represent "5," then the debit total entry circuit is as follows (Fig. 21d):

Debit total entry circuit.—Line 101, make and break contacts 75, contacts 154a (closed except when a credit item is involved), the feeler 77 of emitter E+, spot "5," the common wire 156 of the row of 114b-5 contacts, the closed 114b-5 contacts of the left-hand column, the common wire 157 of the left-hand column of contacts, the left, now closed side of the pair of total 35 entry contacts 130b in series with this common wire 157, magnet CM of column 8 of the total bank, line 102.

In a similar manner, total entry circuits will be formed through the other columns of the 55 total bank, and at the end of the entry period of the second accumulator cycle within the second effective readout cycle, the product will have been read out from the bank of 114b contacts into the total bank.

60 When cam contacts A10 open during the latter accumulator cycle, the common side of the stick circuits of the columns of value coils 114 is opened, parallel contacts 130a having previously been opened by energization of total entry relay magnet 130. The value retaining bank is thus cleared after the product has been entered into the total bank.

CREDIT ITEMS

70 The credit items are either a simple credit, which includes a payment by cash or check (see line 5 of the bill, Fig. 13), or a computed credit, which is the product of factors typed in the quantity and price columns. The computed credit 75 may be the product of returned articles by the

individual price of the article (see item 4 of Fig. 13).

The typing, punching, and entry of a computed credit item, such as item 4 of the illustrative bill (Fig. 13) will be explained first.

The operator proceeds, in exactly the same manner as explained for a debit item, in the typing of the lot number, quantity, price, and description. The typing of the lot number, quantity and price causes concomitant operation of the punching means in the same manner as for a debit item. The typing also causes setting of the value retainer bank, and multiplication begins after entry of the last price digit and continues during the typing of the description. Before depressing the tab key following typing of the description, the operator depresses the credit key CK (see Fig. 1). Depression of key CK closes key contacts CKa and CKb (bottom of Fig. 21a). It will be recalled that the multiplication operation involves the multiplication of the price factor or multiplicand by successive orders of the quantity factor or multiplier and that at the end of the multiplication by the last order of the multiplier, the switch SW—#2 is advanced to position "4," causing formation of the release magnet SWR—2 circuit. In this circuit are also coils 131 and 153 (see Fig. 21e). Coil 131 opens contacts 131a in the common side of the stick circuits of the value coils 114 (Fig. 21c), as a result of which, coil 139 in the stick circuit of the right hand column of value coils is deenergized. Assuming now that multiplication has been completed, coil 139 will be deenergized and relay contacts 139a (middle, left of Fig. 21f) will be in normal condition, with the left side closed and the right side open. The condition of the relay contacts 139a determines whether credit relay coils 155, 150, and 172 are ready to be energized upon depression of the credit key CK. With contacts 139a in normal condition, the closure of credit key contacts CKa establishes the following circuit (Fig. 21f):

Credit coils circuit #1.—Line 102, coils 155, 150, 172, the left side of contacts 139a, connection b—45 (continue with Fig. 21a), contacts CKa, connection b—46 (return to Fig. 21f), wire 173, normally closed 132b relay contacts, connection b—55 (return to Fig. 21a), normally closed error key contacts EKb, connection b—56, line 101.

If multiplication had not been completed at the time the credit key was depressed, the above circuit would not form because the left side of contacts 139a still would be open. Instead, the following circuit would be completed (Fig. 21f):

Credit coil 174 circuit.—Line 102, coil 174, the right, still closed side of contacts 139a, and from there on as in the preceding circuit.

Coil 174 closes stick contacts 174a to maintain the coil energized, after release of the credit key and opening of its contacts CKa, through the following circuit (Fig. 21f):

Credit coil 174 stick circuit.—Line 102, coil 174, contacts 174a, wire 173, contacts 132b, and from there on as in the credit coils circuit #1.

Coil 174 closes contacts 174b to prepare the credit coils 150, 155, and 172 for energization as soon as multiplication is completed and obviates the necessity for the operator to continue holding the credit key down. When multiplication is subsequently completed, the left side of contacts 139a closes and the following circuit forms (Fig. 21f):

Credit coils circuit #2.—Line 102, coils 150, 75

155, 172, the left side of contacts 139a, contacts 174b, line 173, contacts 132b, and from there on as in the credit coils circuit #1.

Coil 172, when energized by either credit coils circuit, closes contacts 172a to directly connect the credit coils 150, 155, and 170 to contacts 132b, and these coils then remain energized until contacts 132b open or unless the error key EK (see Fig. 1) is depressed to open normally closed error key contacts EKb (Fig. 21a).

When the credit key CK was operated, it also closed credit key contacts CKb (Fig. 21a) to establish the following circuit (Fig. 21f):

Credit coil 163.—Line 102, coil 163, connection b—47 (turn to Fig. 21a), contacts CKb, connection b—48, connection b—55, error key contacts EKb, connection b—56, line 101.

Coil 163 closes contacts 163c to provide a stick circuit as follows (Fig. 21f):

Credit coil 163 stick circuit.—Line 102, coil 163, contacts 163c, normally closed relay contacts 171a, connection b—55 (turn to Fig. 21a), error key contacts EKb, connection b—56, line 101.

Coil 163, while energized, holds contacts 163b in clutch circuit #2 (Fig. 21f) open to prevent formation of this circuit until the credit section of the bill is brought to typing position. Coil 163 also opens contacts 163a in the coils 149 and 161 circuit (Fig. 21e) to prevent energization of these coils before the credit section of the bill is reached. It will be recalled that when the debit section of the bill is tabulated to typing position, coil 162 is energized and closes contacts 162a in the coils 149 and 161 circuit. When dealing with the credit item, the credit key is depressed and coil 163 energized to open contacts 163a in the coils 149 and 161 circuit. Consequently, after typing the description, when the operator tabulates to the debit section, the closure of contacts 162b will not complete the coils 149 and 161 circuit even though contacts 465a may have been closed as a result of column 33 of the card having reached punching position. Hence, the credit product will not be read out into the debit section. The operator must then depress the tab key twice to tabulate the first column of the credit section to typing position. This advances switch SW—#3 (Fig. 21f) from position "6" to position "8," causing the following circuit to form (Fig. 21f):

Coil 177 circuit.—Line 101, position "8" of switch SW—#3, socket 103—8, plug wire 104 to socket 105—4, coil 177, line 102.

Coil 177 opens contacts 177a in the credit coil 163 circuit, deenergizing coil 163 to permit contacts 163a and 163b, respectively in the coils 149 and 161 circuit and clutch circuit #2, to reclose.

The formation of the coils 149 and 161 main circuit (Fig. 21e) through contacts 162a cannot occur because the coil 162 is not now energized. Coil 171, instead, is now energized and closes contacts 171b, in parallel with contacts 162a, to replace the latter in the coils 149 and 161 circuit. When multiplication is completed, coil 131 is energized by the release magnet SWR—2 circuit, coil 131 closes contacts 131b to complete the coil 160 circuit, and energization of coil 160 is then maintained through the stick circuit extending through reset contacts RMa—P. Coil 160 closes contacts 160a in the main circuit of coils 149 and 161. Contacts 465a close when coil 465 (Fig. 21g) is energized as a result of column 33 of card W arriving at punching position. With contacts 160a, 163a, 171b, and 465a all closed, when cam contacts R2 also close (see Fig. 20b), the circuit

of coils 149 and 161 is completed. Coil 161 closes contacts 161a to form the stick circuit of the coils through cam contacts R1.

To recapitulate, the formation of the coils 149 and 161 main circuit, after depression of the credit key, requires completion of multiplication with resultant closure of contacts 160a, the tabular spacing of the credit section of the bill to typing position, and the arrival of the first column of the amount field of the card W in punching position. The completion of multiplication, together with operation of the credit key, causes the formation of a circuit through credit coils 150, 155, and 172 (Fig. 21f). Thus, at this point, coils 160, 149 and 161, 171, 150, 155, 172, and 465 (also 468) are energized.

When coil 163 was deenergized, contacts 163b in the circuit of clutch magnet 40 (Fig. 21f) reclosed. Coil 171, now energized, closes contacts 171c in series with contacts 163b, and energized coil 160 closes contacts 160c. With all these contacts closed, a circuit through clutch magnet 40 is completed, similar to clutch magnet circuit #2. Coil 149, now energized, closes contacts 149c to form the coil 148 circuit (Fig. 21f). Coil 148 closes stick contacts 148b to provide a stick circuit for the coil through cam contacts A11. Coil 148 closes contacts 148c to continue the clutch magnet energized after contacts 171c open as a result of deenergization of coil 171, occurring when the tabular spacing from the dollars field of the credit section to the cents field advances switch SW—#3 to position "9." Accordingly, two read out cycles for the credit product will be performed, just as when a debit product was read out.

Coil 161 closes contacts 161b in the common line of the product auto type emitter E—P (see Fig. 21b). The credit product is then read out through emitter E—P from the product bank by formation of the product auto type circuits, which are the same for debit or credit products, and the credit product is typed in the credit section of the bill.

When coil 149 was energized, it closed contacts 149b to form the circuit of coil 111 (Fig. 21e). Consequently, contacts 111d (Fig. 21g) are closed and multi-contact relay magnet PM is energized. Accordingly, typing of the credit product will cause punching of the corresponding digit designations in the amount field of card W. The amount field consists of columns 33 through 40. For item 4 of the illustrative bill, the credit product is 41.70 hence the first four columns of the credit field of the bill will be spaced past the typing point by operation of space key solenoid 30—SP while the first four columns 33 through 36 of the card will be punched with zero designations.

To classify the card W as a credit item card when it is punched in the amount field with a credit amount, it is desired to punch column 35 in the X position. The punching of the X perforation in column 35 results in the feed of column 36 to punching position. However, it is necessary to punch column 35 not only with the X credit classification but also with a digit designation which may be 0 or 1 to 9. Accordingly, means are provided to punch column 35 simultaneously with the selected digit designation and with the X designation. Reference to Fig. 21g shows that for this illustrative case, column 35 commutator contact 424 is plugged to a relay coil 485. When column 35 reaches punching position, the following circuit is completed:

Coil 485 circuit.—Line side 453, contacts 403, contacts 457a and 370, connections P7 and P8, commutator common 425, brushes 423 and 422, column 35, contact 424, plug connection to coil 485, and through the coil to line side 452.

Coil 485 closes its contacts 485a (Fig. 21g).

Credit coil 150 (Fig. 21f) remains energized during credit typing and punching. Accordingly, contacts 150c (Fig. 21g) are now shifted. Also, as explained before, magnet PM is energized; hence, contacts PMa and PMb are now closed. As described before, when a digit key is operated, the coil 120 circuit is established through the key contacts 28 (Fig. 21a). On the other hand, when the space bar is operated, the coil 140 circuit is made through contacts 28—SP (Fig. 21a). Accordingly, with either coil 140 or 120 energized while column 35 of the card is in punching position and contacts PMb, the left side of contacts 150c, and contacts 485a all closed, the following circuit is established (Fig. 21g):

X punching (column 35).—Line side 453, contacts 457a contacts 370, connection p7, contacts PMb, either contacts 120c or 140c, the left side of contacts 150c, the switch 486 in dotted position, contacts 485a, the X key magnet 323 and through resistance to line side 452.

It may be pointed out that if an X hole were to be punched to classify debit instead of credit data, the switch 486 would be set in full line position. When a debit is being typed and punched, the credit coil 150 is not energized. Hence, contacts 150c will remain in normal position. The X punching circuit would then form through the right side of contacts 150c and the switch 486 in plus position to classify a debit card.

However, it is assumed that a credit card is to be punched with the X hole in column 35 so that under the stated credit condition, the X key magnet 322 has been energized. At the same time, through closure of key contacts 28p, the punch magnet selection circuit is established to energize one of the key magnets 322—0 to 9. Accordingly, the selected digit designation 0 to 9 and the X designation will be simultaneously punched in column 35.

When coil 149 was energized, it closes contacts 149b to form the circuit of coil 111 (Fig. 21e). Credit coil 172 has also closed contacts 172b, in shunt with contacts 149b, but the former contacts are necessary only for the entry of a simple or cash credit, which will be explained later, during which entry the coil 149 is not energized and contacts 149b are not closed. Coil 111 closes contacts 111a (Fig. 21a) to enable the credit product, while being typed into the credit section, to be entered in the value retainer bank, just as when a debit product was typed into the amount section. The purpose of setting up the value retainer bank with the typed product is to control entry of the product into the total bank.

The debit product was entered into the total bank additively. The credit product must be entered subtractively through credit emitter E— (Fig. 21d) into the total bank, and entry through the debit emitter E+ must be prevented. The common side of the entry paths through emitter E+ includes contacts 154a closed by normally energized coil 154, as explained before. When a credit item is being dealt with, the credit coils 150, 155, and 172 are energized in the manner explained above. Coil 155 opens contacts 155a in the coil 154 circuit (Fig. 21f), deenergizing coil 154 and causing contacts 154a to open, thus

breaking the connection of emitter E+ to line 101. Coil 155 also closes contacts 155b, connecting the feeler of credit emitter E-, through make and break contacts 75, to common line 101.

Energized coil 148 has closed contacts 148d (top of Fig. 21f) and entry into the right-hand column of the value retainer bank of the units of cents product digit has energized magnet RH to close contacts RH₁ in series with contacts 148d. The cam contacts A1 then close and the main circuit of total entry magnet 130 is formed, followed by the stick circuit extending through contacts 130c and cam contacts A6. Energization of magnet 130 shifts the center blades of the group of 130b contacts (Fig. 21d) to connect the columns of 114b contacts to the total bank. As shown in Fig. 21d, the credit emitter E- has its spots "8" to "1" respectively connected by wires 170 to complementary spots "1" to "8" of the plus emitter E+. Thus, when the plus emitter is operative to cause entry through the retainer relay bank of b contacts into the total bank, the plus value of the amount represented by the position of the closed 114b contacts is entered. When the credit emitter is operative, the entry through the same closed 114b contacts is in complementarily timed relation to the amount represented by the closed 114b contacts, so as to enter the "9" complements of the amount into the total bank. Assume, for example, that the highest or eighth order of the credit amount contains digit "5", now represented by closed contacts 114b-5 of the left-hand column. The credit entry circuit then is formed at the "4" point of the accumulator cycle, as follows (Fig. 21d).

Credit entry circuit.—Line 101, contacts 75, contacts 155b, the feeler of the credit emitter E-, spot "4" thereof, connection 179 to common wire 156 of the row of 114b-5 contacts, closed, 40 contacts 114b-5 of the left-hand column, the left side of the connected pair of 130b contacts, magnet CM of column 8 of the total blank, line 102.

Thus, the "nine" complement "4" of the credit digit "5" is entered into the total bank.

Through similar circuits, the complements of the other digits "1" to "8" of the credit amount are entered into the total bank. When a credit digit "0" has been set up in the value retainer bank, the credit entry circuit enters the complement "9", as follows:

Complement of "0" credit entry.—Line 101, contacts 75, contacts 155b, the feeler of emitter E-, the "9" spot thereof, contacts 155c, the closed 114b-0 contacts, the left side of the connected contacts 130b, the related magnet CM of the total bank, line 102.

If a space bar operation is effected to skip entry into a column of the value retained bank, then a value coil stick circuit for this column will not be formed. In the stick circuits of the several columns are coils 125, 133, 134, 135, 136, 137, 138, and magnet RH (see Fig. 21c). Failure of any of these coils or of magnet RH to be energized causes associated contacts 125c, 133c, 134c, 135b, 136b, 137b, 138b, or RH₁ (top of Fig. 21d) to remain closed. When dealing with a credit setup, the value "9" is entered into the total bank column connected to that value retainer column in which one of the latter contacts remain closed because of the space bar operation which skipped entry into this value retainer column. For example, if the left-hand value retainer column has not been set up, contacts 125c remain closed, and "9" will be entered in column 8 of the total

bank through a circuit which begins the same as the preceding circuit, but branches off from contacts 155c to a wire 180 contacts 125c, the common wire 157 of the left-hand column, the left side of connected contacts 130b, magnet CM of column 8 of the total bank, line 102.

In above manner, when a column of the value retainer bank has not been set up because the corresponding credit column of the credit section 10 has been left blank, the value "9" is entered in the corresponding total bank column just as though a zero had been typed in the credit column.

If the credit digit in a denominational order is 15 "9", the complement "0" need not be entered as it would not affect the result.

The elusive one is entered into the units order by energization of the elusive one magnet ELM (see Fig. 4) through the following circuit (Fig. 20 21f):

Elusive "1" magnet circuit.—Line 101, cam contacts A8 (see Fig. 20a), credit relay contacts 150b, total entry relay contacts 130d, magnet ELM, line 102.

Magnet ELM unlatches element 55 (Fig. 4) from the arm 56 of the units order of the total bank, and the arm moves to the left to be subsequently returned by carry bail 60 during the carry over period of the cycle for adding the elusive one to the units order of the total bank, as explained hereinbefore.

The typing of the units of cents credit digit causes energization of coil 139 of the stick circuit of the right-hand column of value coils 114 (Fig. 21c). Coil 139 closes contacts 139b to cause entry of a "9" into column 9 of the total bank as a manifestation of a credit entry. When the feeler of the credit emitter wipes the "9" spot, a circuit is established which begins as in the other credit entry circuits and proceeds from the "9" spot of emitter E- through contacts 139b, magnet CM of column 9 of the total bank, and to line 102. This results in entry of "9" into column 9 of the total bank.

When the feeler of the credit emitter wipes the "0" spot, the following circuit forms (Fig. 21d):

Coils 132 and 142 circuit.—Line 101, contacts 75, contacts 155b, feeler 77 of emitter E-, spot "0", wire 181 (continue with Fig. 21e), total entry relay contacts 130e (now closed), coils 132 and 142, line 102.

Coil 132 closes contacts 132c to provide a stick circuit extending through cam contacts A4 (Fig. 20a).

Coil 132 opens contacts 132a common to the stick circuits of value coils 114 (Fig. 21c).

Coil 132 also opens contacts 132b common to the circuits of credit coils 150, 155, 172, and 174 (Fig. 21f), causing deenergization of these credit coils.

Coil 142 opens contacts 142a in the coil 111 circuit #2 (Fig. 21e), which was formed as a result of closure of contacts 134b when coil 134, in the third value retainer column from the left (Fig. 21c), was energized.

SIMPLE CREDIT ITEM

Line 5 of the illustrative bill (Fig. 13) shows a simple credit item, which does not involve entry into the quantity and price sections. As a result of the previous carriage return operation, the beginning of line 5 is in typing condition. Also, column 1 of a card W is in punching position. The operator's first step in making the simple credit entry is to depress either the total key TK

(Fig. 21a) or the Tab key. Assume the Tab key is depressed first. This brings the lot number field to typing position and places switch SW-#3 in position 1 (Fig. 21f). Consequently, coil 460 is energized, contacts 460a (Fig. 21g) are closed, and punch relay magnet PM is energized.

The next operation is to depress total key TK (Fig. 21a) establishing the following circuit:

Coil 171 circuit.—Line 101, connection b-44, key contacts TK', connection b-42 (turn to Fig. 21f), coil 171, line 102.

Coil 171 closes stick contacts 171b to provide the following holding circuit:

Coil 171 holding circuit.—Line 102, coil 171, contacts 171b, normally closed contacts 143c, 15 155d, and 186a, to line 101.

A card W is at this time in column 1 position. Column 1 commutator contact 424 (Fig. 21g) is plugged to a relay coil 487, establishing the following circuit:

Coil 487 circuit.—Line side 453, contacts 403, 457a and 370, connections p7 and p8, commutator common 425, brushes 423 and 422, contact 424-1, plug connection to coil 487, and through the coil to line side 452.

Coil 487 closes its contacts 487a. These contacts are connected to hand switch 488. When the total key is operated and the coil 171 circuit established and held, contacts 171d in series with switch 488 are closed. Also, as magnet PM is energized, contacts PMb are closed. The following circuit is established (Fig. 21g):

X punching (column 1).—Line side 453, contacts 403, 457a and 370, connection p7, contacts PMb and 171d, post p13 switch 488, contacts 487a, 35 X key magnet 322, and through resistance to line side 452.

As described before, the skip bar 360 (Fig. 19) is contoured to cause skipping, after X punching of column 1, to column 15. Thus, the card W to be punched with the simple credit item is punched in column 1 with a classifying perforation X and skipping of the card effected to bring column 15 to punching position. At this point, the pattern card control comes into play, as explained before, and causes punching of the account data in columns 15 through 32 of the card.

After having depressed the total key to cause the X punching and skipping of the card, the operator tabulates the description field of the bill to typing position and types the description. It may be noted that the typing of the description does not cause punching operation since switch SW-#3 (Fig. 21f) is then in unplugged position 5 and punch relay magnet PM is not energized. After typing the description, the operator, by repeated depressions of the tab key, brings the credit section of the bill to typing position. The credit key is depressed after the description is typed and before or after tabulating the credit section to typing position but prior to typing of the simple credit. When the credit key is depressed, the credit coils 150, 155, and 172 (Fig. 21f) are energized by credit coils circuit #1.

Coil 150 opens contacts 150a in the switch SW-#2 to prevent operation of this switch when contacts RH₂ subsequently close as a result of the typing of the units cents order digit of the simple credit. Coil 155 opens contacts 155a in the circuit of coil 154 (Fig. 21f) to cause the opening of contacts 154a (Fig. 21d) connecting the debit emitter E+ to line 101. Coil 155 also closed contacts 155b, connecting the credit emitter E- to line 101, and closes contacts 155c 75

connecting the "9" spot of this emitter to the "0" row of contacts 114b and to line 180 for reading out a complement "9" from a column of contacts 114b which has either been set to represent "0" or has not received any entry.

Coil 172 closes contacts 172b (Fig. 21e), parallel with contacts 110a and 149b, to form the circuit of coil 111. Coil 111 closes contacts 111a (Fig. 21a) to enable the operation of the digit keys, in typing the simple credit, to enter the credit value into the value retainer bank. Contacts 111d (Fig. 21g) also close to energize punch relay magnet PM. Coil 155 also opens contacts 155d (Fig. 21f) in the holding circuit of coil 171. Consequently, contacts 171d (Fig. 21g) open. Coil 172 also closes contacts 172c, in shunt with contacts 148d, to prepare the total entry magnet 130 (top of Fig. 21f) for subsequent energization.

20 The operator, after depressing the credit key and tabulating the credit section of the bill to typing position, types the simple credit value. During typing of this value, punching of the amount field of the card takes place in the manner explained before. Also, since credit relay contacts 150c are in shifted condition, the previously traced X punching column 35) circuit will be established to characterize the card as a credit card. During typing and punching of the simple credit, the coils 114 of the value retaining means are energized to store the simple credit amount. Entry of the last digit into the last column of the value retainer means causes energization of magnet RH. The contacts RH₂ thereupon close to form clutch magnet circuit #1. Contacts RH₂ close, credit coil contacts 172c have been closed before, and when cam contacts A7 close, the circuit of total entry magnet 130 (Fig. 21f) is formed. Accordingly, the simple credit, just as the computed credit, will be entered during an accumulator cycle into the total bank. The auto carriage return operation occurs under control of the punch unit upon eject of the card, as explained before.

45 It should be noted that the purpose of contacts 143c in the holding circuit of coil 171 is to enable this circuit to be opened upon operation of error key EK. As explained before, operation of this key energizes coil 143 (Fig. 21b). Contacts 143b established the circuit of release key magnet 322-R (Fig. 21g), the result of which is initiation of an eject and card feed cycle. Also, contacts 143c open, breaking the holding circuit of coil 171, so that X punching in column of the new card will not occur unless the total key is again depressed.

TOTAL OPERATIONS

60 The total bank carries the accumulation or balance of the debit and credit items entered on the bill. This total may be read out and automatically typed in the total section of the bill and punched in the amount field of the card W. The total readout operation requires the depression of either total key TK and TRK (Fig. 1) and the tabular spacing of the carriage to bring the total section to typing position. The key TK is used if the total is to be read out without accompanying reset of the total bank, while the key TRK is used when it is desired to take the total and also to effect reset. For example, the key TK is used when two bills are to be sent to the same customer, with the total of the first bill to be carried forward to the second bill.

70 The total line of the bill is now in typing po-

sition and column 1 of a cord W is in punching position. The first operation is to tabulate the bill sheet to the lot number field. Through switch SW-#3, coil 460 is energized. Contacts 460a (Fig. 21g) close, and magnet PM is energized.

Total taking without resetting.—Assuming that it is desired to take a total without resetting, the operator depresses the total key TK, closing contacts TK' to form the previously traced coil 171 circuit which is followed by the holding circuit of this coil. Contacts 171d (Fig. 21g) close and, consequently, X punching of column 1 of the card and skipping to column 15 occur, as described before. The pattern card data is then duplicated in columns 15 through 32 of the card. Unlike the case of punching of the simple credit item, the credit key is not depressed. Hence, the holding circuit of coil 171 remains effective until contacts 186a open. The latter contacts do not open until after the total relay coils circuit is established, as will be explained below. Coil 171 also closes contacts 171c (Fig. 21f) in the line leading to plug socket 105-5, which is connected to plug socket 103-10, corresponding to the total section. Nothing further happens until the operator tabulates the total section to typing position. When this is done, switch SW-#3 advances to position "10", and with contacts 171c closed, the following circuit forms (Fig. 2):

Coil 187 circuit.—Line 101, position "10" of switch SW-#3, socket 103-10, the plug wire to socket 105-5, contacts 171c, coil 187, line 102.

As a result of operation of the key TK, the total key circuit, energizing coil 171, has been established, and when the total section is tabulated to typing position, the coil 187 circuit also forms.

Coil 187, upon energization, closes contacts 187a to by-pass contacts 171c and maintain the coil energized while the switch SW-#3 remains in position "10", which it does throughout total recording. Coil 187 also closes contacts 187b to establish a circuit for clutch magnet 40 (Fig. 21f) extending through contacts A9 to initiate two readout cycles of calculator shaft 36. During the first readout cycle, cam contacts R4 (see Fig. 20b) close and, with contacts 187c also closed by the energized coil 187, the following circuit will form if the punch control switch SW-SP is in "off" position (start with Fig. 21e):

Total relay coils circuit.—Line 101, cam contacts R4, connection b-77 (turn to Fig. 21a), switch blade #1, connection b-78 (return to Fig. 21e), contacts 187c, total relay coils 117, 186, and 188, line 102.

Assuming, however, that switch SW-SP is in "on" position and the punch unit is being operated together with the typewriter and calculator, the above circuit will not be established. An alternative circuit will be made upon closure of relay contacts 468a, shunting switch blade #1. In the description of the debit entry, it was explained that the coils 465 and 468 circuit (Fig. 21g) is completed when the card carriage, after the pattern data has been punched, reaches the column 33 position. In this position, the first column of the amount section of the card is in punching position, coil 468 is energized, and its contacts 468a (Fig. 21e) close to complete the circuit of the total relay coils.

Total coil 117 closes stick contacts 117b to hold the total relay coils energized through cam contacts R3. In the foregoing manner, the initia-

tion of the total readout, which as will be clear later, requires energization of the total coils, is delayed until both the bill and the card have been brought to required recording positions.

- 5 Coil 186 closes contacts 186b (Fig. 21f) in parallel with contacts 187b in the clutch magnet circuit. Contacts 186a in the stick circuit of coil 171 (Fig. 21f) open, deenergizing this coil. Coil 186 also closes contacts 186c which are in shunt with contacts 186c (Fig. 21a) to replace the latter in the holding coil 167' circuit, which will form as a result of the read out of the first signification figure, prior to which contacts 167b will divert the "0" dollars readout circuit to the space solenoid 30-SP, as explained hereinbefore.

Coil 186 closes contacts 186d and when cam contacts R7 close, the following circuit forms (Fig. 21b):

- 20 *Credit balance control magnet 189.*—Line 101, contacts R7, contacts 186d, plural coil magnet 189, line 102.

When the total bank carries a net debit or positive balance, magnet 189 performs no function. Assuming there is a debit balance, it will suffice, for the present, to state that magnet 189 is deenergized when contacts R7 open before the beginning of the readout period at "8" of the readout cycle (Fig. 20b).

- 30 After cam contacts R7 open, cam contacts R8 close, and with contacts 117c closed by total relay coil 117, the following circuit forms (Fig. 21f):

35 *Total control magnet 190.*—Line 101, cam contacts R8, contacts 117c, magnet 190, line 102.

Magnet 190 closes the group of contacts 190a at the right of the commutator TRO (Fig. 21b).

- 40 Coil 117 also opens contacts 117a (Fig. 21a) common to the coil 120, coil 140, and the key coil circuit to prevent possibility of the value retaining means being set up as a result of the automatic typing of the total which is to take place.

Coil 188 closes contacts 188b (Fig. 21g) to form the circuit of punch relay magnet PM. Accordingly, during read out and typing of the total, the punch unit will be operated to punch the total in the amount section.

- 50 Coil 117 also closes contacts 117d between the feeler of the auto type total emitter E-T (Fig. 21b) and line 101.

Debit balance readout.—Assuming that the bill total is a plus or debit total, and that the reading in column 8 of the total bank is "5", then the total readout circuit is as follows (Fig. 21b):

- 55 *Debit total readout circuit.*—Line 101, contacts 83, contacts 117d, normally closed contacts 191a, the feeler of emitter E-T, emitter spot "8", a normally closed pair of contacts 164b, the serially connected, normally closed side of relay contacts 207a, the + collector ring of column 8 of total bank commutator TRO, the + brush 51 of column 8, segment 53-5 now engaged by the + brush, the serially connected, now-closed contacts 190a, the serially connected, normally closed side of inversion relay contacts 193a-5, connection b-16 (turn to Fig. 21a), key solenoid 30-5, connection b-9, pickup coil 167, line 102.

The solenoid 30-5 operates the key 10-5 to type "5" in the first column of the total section of the bill. The function of coil 167 is the same as described in connection with the read out of the product. The closure of key contacts 28p-5 (Fig. 21g) completes the circuit of punch key

magnet 322—5, causing column 33 to be punched with a 5 designation.

Through similar total circuits, digits 1 to 8 are read out of the other total bank columns and automatically typed and punched. The readout of zeros in columns 8 to 3 of the total bank is also effected through a similar auto type circuit, but which includes closed "0" test contacts for a reason which will be made clear later. The readout of zeros from columns 1 and 2 is through a slightly different circuit, which will be traced later. Likewise, the readout of "9" from the total bank columns is through circuits which depart somewhat from the above-traced total readout circuit. Thus, the readout circuit for a "9" from dollars columns 8 to 3 proceeds from the "9" segments 53 of these columns through the left, normally closed side of contacts 194a to the "9" segments of columns 1 and 2, through the closed side of contacts 194b, a pair of total control relay contacts 190b, contacts 193a—9 connection b—20 (turn to Fig. 21a), solenoid 30—9, connection b—9, coil 167, line 102. The "9" readout circuit for columns 1 and 2 differs from the above-traced circuit in omitting contacts 194a.

Between the units of dollars column and the dimes column of the total field of the bill, a tab space is preferably provided. The tabular spacing operation between these columns is automatically effected under control of the auto-type total emitter E—T when the feeler thereof engages the "tab" spot of the emitter, in the same manner as explained in connection with the read out of the product through the product emitter E—F, the "tab" spots of the two auto-type emitters being connected to each other (see Fig. 21b).

When the last digit of the total has been typed and punched, the card carriage escapes to the last column position and the card is ejected. During eject, contacts 392 complete the circuit of coil 480. Coil 480 closes contacts 480a (Fig. 21a) to complete the previously traced circuit of carriage return solenoid 30—CR.

Total taking and resetting.—Between the "reset spot" of total emitter E—T and the reset magnet RM—T of the total bank is a pair of relay contacts 195a, which remain open when the key TK is operated to cause total taking operation without accompanying resetting. When total taking and resetting are both required, the total operation is initiated, by depressing the total and reset key TRK to close contacts TRK', forming the following circuit (begin with Fig. 21a):

Total and reset key circuit.—Line 101, connection b—44, contacts TRK', connection b—43 (continue with Fig. 21f), pick-up coil 185, coil 171, line 102.

The above circuit energizes coil 171 just as when the total key circuit was formed as a result of operation of the total key TK. All the total taking operations, described above as initiated by operation of the key TK, now take place as a result of the operation of key TRK to energize coil 171. In addition, however, the total and reset key circuit has energized pick-up coil 185. The latter thereupon closes contacts 195b to establish the circuit of holding coil 195' as follows (Fig. 21e):

Holding coil 195' circuit.—Line 101, total bank reset contacts RMa—T, contacts 195b, coil 195', line 102.

Coil 195' now remains energized until contacts RMa—T open during resetting of the total bank. Energization of coil 195' maintains con-

tacts 195a (Fig. 21b) closed, so that when the feeler of emitter E—T reaches the "reset" spot during readout of the total bank, the reset magnet RM—T is energized to cause resetting of the total bank.

Credit balance readout.—It has been assumed that the net balance standing in the total bank is a plus or debit balance. If the credits exceed the debits, then the net balance will be a credit or minus balance. The grand total, debit or credit, to be accumulated in the present case, is not to exceed eight denominational orders and is within the capacity of columns 1 to 8 of the total bank. It will be recalled that when a credit was entered in the total bank, a "9" was entered in column 9 of the bank. If the net balance is a debit total, then carry-over will have been effected to column 9 to bring its reading to "0". If the net balance is a credit total, then the 9th column will read "9". When this is the case, the remaining columns of the total bank carry the complement of the credit or minus balance. This complement must be converted into the corresponding true number and typed as such in the total section of the bill.

In the same manner as explained for the debit total taking operations, the total relay coils circuit is formed, followed by the closing, through cam contacts R1 and 186d, of the credit balance control magnet 189 circuit (Fig. 21f). Magnet 189 closes the group of 189a contacts and also the pair of contacts 189b (Fig. 21b). Now, with ninth column of the total bank reading "9", indicating a credit balance, the following circuit forms (Fig. 21b):

Credit balance pick-up coil 196.—Line 101, the common side of the 189a contacts, the left-hand pair of these contacts, a pick-up coil 196, the + collector ring of column 9 of the readout commutator TRO, the + brush 51 thereof, the "9" digit segment 53 of the 9th column, through the connected row of "9" digit segments of the columns 8 to 3, the left side of contacts 194a, the "9" segments of columns 1 and 2, a wire 197, contacts 189b, a coil 198, line 102.

Coil 196 closes contacts 196a to energize the holding coil 196', as follows (Fig. 21e):

Coil 196' circuit.—Line 101, cam contacts R6, contacts 196a, coil 196', line 102.

The credit balance control magnet 189 is de-energized, and the credit balance pick-up coil 196 circuit broken, when cam contacts R1 (Figs. 20b and 21f) open, but coil 196' remains energized and holds contacts 196a closed until contacts R6 open after the first or lowest order column of the total bank has been read out.

When the credit balance pick-up coil 196 circuit breaks, coil 198 is deenergized and its contacts 198a close. Since contacts 196a also are closed, the following circuit forms (Fig. 21e):

Inversion magnet.—Line 101, cam contacts R6, contacts 196a, 198a, in parallel through coil 194 and inversion relay magnet 193, line 102.

Magnet 193 shifts the center blades of the group of contacts 193a—0 to 9 (Fig. 21b), opening the normally closed side of these contacts which are in the debit total readout circuits. The closing of the normally open sides of contacts 193a connects segments 53 of the readout commutator TRO to the complementarily related key solenoids 30, causing the complement of the credit balance in the total bank to be read out and typed and punched as a true credit balance. Contacts 193a are shifted as a result of the energization of magnet 193 when contacts 198a

close, which is timed by opening of cam contacts R7 to occur before cam contacts R8 close. When the latter cam contacts close the total control magnet 190 circuit (Fig. 21f) is established to energize magnet 190 which closes the group of 190a contacts (Fig. 21b). Assuming for example, that column 8 of the total bank reads "6", the following circuit forms (Fig. 21b):

Credit total readout circuit.—Line 101, contacts 83, contacts 117d, 191a, the feeler of emitter E—T, the "8" spot thereof, the connected 164b contacts, the normally closed side of contacts 207a, the + collector ring of column 8, the + feeler thereof, the "6" segment, the contacts 190a in series with the connected "6" segments, the lower, now-closed side of inversion contacts 193a—3, connection b—14 (continue with Fig. 21a), solenoid 30—3, connection b—9, coil 167, line 102.

This circuit causes typing of "3" as a result of the credit reading of "6" in column 8 of the total bank. The operation of the 3 typing key also causes punching of a 3 designation. In a similar manner, the "9" complements of values in all the other columns of the total bank, except the units order column, are read out and typed. The "9" credit value readout circuit of columns 8 to 3 proceeds from the "9" segment of column 3 through the lower, now-closed side of contacts 194b (coil 194 has been energized by the inversion magnet circuit), through contacts 190b, the lower, now-closed side of inversion contacts 193a—0, line 168 (turn to Fig. 21a), the center blade of contacts 167b, and from there either to the "0" or the space bar solenoid 30, depending on the condition of contacts 167b which, in turn, depends on whether a significant digit has been read out from a higher order column. Thus, the nine complement "0" of a "9" in columns 8 to 3 is normally read out by the above circuit. For a credit reading of "9" in column 2 (the tens of cents order), it is desired normally to type a "0", regardless of whether a significant dollars digit has or has not been printed. The "9" credit readout circuit of column 2 proceeds from the "9" segment of this column to the right, now-closed side of contacts 194a, through a wire 199, the wire 170 (turn to Fig. 21a), and the connection b—11 to solenoid 30—0. In column 1, the units order column, the "10" complement of the credit value must be read out and typed. Thus, if the + feeler of column 1 is on segment 53—0, then "0" must be read out. When inversion magnet 193 was energized, it also closed the left side of contacts 193b and opened the right side, connecting the "1" spot of emitter E—T to the minus collector ring of column 1 and disconnecting the "1" spot from the + collector ring of this column. The — brush, as explained hereinbefore, is one step behind the + brush. Thus, if the + brush is on "0", then the — brush is in the "9" segment (see Fig. 3a). The circuit for the units order complement of credit reading "0" is then as follows (Fig. 21b):

"0" units order credit readout.—Line 101, contacts 83, 117d, 191a, the feeler of emitter E—T, the "1" spot, the left side of contacts 193b, the — collector ring of column 1, the — brush thereof, the "9" segments 53 of columns 1 and 2, the right side of contacts 194a, wire 199, wire 170, connection b—11, solenoid 30—0, connection b—10, line 102.

Similarly, any other credit value in column 1 is read out through the — brush of this column

in order to provide the "10" complement thereof. For example, if the units order column + feeler is on the "6" segment, the — feeler is on the "5" segment. With the left side of contacts 193b closed, the readout circuit for the first column proceeds from spot "1" of emitter E—T through the left side of contacts 193b, to the — collector ring, the — brush, the segment "5", the connected points 190a, the now-closed, lower side of contacts 193a—4, connection b—15 (continue with Fig. 21a), solenoid 30—4, connection b—9, coil 167, line 102. As a result, the "10" complement, "4", of the units order credit reading of "6" is typed.

In reading out the "10" complement of the credit reading in column 1, the elusive one for this column has been taken care of. The reading out of "9" complements of the credit values in other columns has also been explained. However, if the units order reads "0", then the elusive one must also be added to the tens order, and if the tens order also reads "0", then the elusive one must be added to the hundreds order, and so on. Thus, under the above conditions, the elusive one must be added not only to the units order but to all the orders to the left thereof and including the first one containing a significant figure, just as though the latter were really the units order. In other words, the first significant digit from the right and the "0" digits in all the orders to the right of this first significant figure must be read out as "10" complements, while the digits in the orders to the left of the first significant figure must be read out as "9" complements. For example, the real number corresponding to the complement of 99,082,000 is 00,918,000. When the complementary figure 99,082,000 is standing in the first eight columns of the total bank, then the ninth column also reads "9", manifesting a credit balance. With this complementary reading in the total bank, the ninth column commutator + brush 51 is on the segment "9"; in the eighth and seventh columns, the + brushes are on the segments "9" and the — brushes on the "8" segments. In the sixth column, the + brush is on segment "0" and the minus brush on segment "9"; in the fifth column, the + brush is on segment "8" and the minus brush on segment "7"; in the fourth column, the + brush is on segment "2" and the minus brush on segment "1"; and in the third, second, and first columns, the + brushes are on segments "0" and the — brushes on the "9" segments.

When the credit balance control magnet 189 was energized, as previously described, it closed the group of 189a contacts (located above the total emitter E—T, Fig. 21). Between these several contacts and the minus collector rings of columns 1 to 7 are elusive one pick-up coils 201, 202, 203, 204, 205, 206, and 207. Simultaneously with formation of the circuit of coil 196, traced before, through the left-hand pair of contacts 189a, the following parallel circuit is completed as a result of the — brush of the column 1 engaging the "9" segment (Fig. 21b):

Elusive one pick-up coil 201.—Line 101, the common of the 189a contacts, the first pair of 189a contacts from the right, pick-up coil 201, the minus collector ring of column 1, the "9" segment thereof, wire 197, contacts 189b, coil 198, line 102.

Similarly, elusive one pick-up coils 202, 203, and 206, respectively associated with the second, third, and sixth columns, are energized as a re-

sult of their — brushes engaging "9" segments. The elusive one pick-up coils 204, 205, and 207 are not energized because the — brushes of columns 4, 5, and 7 are not engaged with "9" segments. It may be noted that an elusive one relay coil is not provided for the eighth column because if this column reads "0" and the other columns to the right also read "0", then the net balance is zero, and means are provided, in that case, to prevent any auto total readout operations, as will be explained later.

At this time, for the assumed example, the pick-up coils 196, 201, 202, 203, and 206 are energized and respectively close contacts 196a, 201b, 202b, and 206b (bottom of Fig. 21e). A circuit thereupon is established from line 101, through cam contacts R6, contacts 196a, wire 208, contacts 201b, holding coil 201', to line 102. The circuit of holding coil 202' is formed similarly through serially connected contacts 201b and 202b, and for holding coil 203 through serially connected contacts 201b, 202b, and 203b. The circuit of holding coil 206' cannot form because the contacts 204b and 205b are open, breaking the connection between closed contacts 203b and 206b. Thus, energization is effected only of the elusive one holding coils which are related to the columns of the total bank which read "0" to the right of the first right hand significant figure. When cam contacts R7 open, the magnet 189 is deenergized, its contacts 189a and b open, and the elusive one pick-up coils are deenergized.

Coils 201', 202', and 203' open the normally closed, right sides of their respective contacts 201a, 202a, 203a, and close the left sides, thereby disconnecting the + collector rings of columns 2, 3, and 4 from spots "2," "3," and "4" of emitter E—T and connecting the — collector rings of these columns to these emitter spots. The readout circuit for the column 4 proceeds, then, from spot "4" of the emitter E—T, through the left, now closed side of contacts 203a, the — collector ring of column 4, the — brush thereof, the segment 53—1 engaged therewith, the associated pair of contacts 190a, the now-closed, lower side of inversion contacts 193a—8, connection b—19 (continue with Fig. 21a), solenoid 30—8, connection b—9, coil 167, line 102.

Thus, with the credit value "0" in each of columns 1, 2, and 3, the credit digit "2" in column 4 of the card is read out as its "ten" complement "8." The "0" in each of columns 1, 2, and 3 is read out through circuits such as traced previously through the "9" segments of these columns, with the difference for columns 2 and 3 being in the routing of the circuits through their — collector rings and — brushes.

The punching of a credit or negative balance on the card must be identified as such on the card. This is done by punching the X hole in column 35 as was done in the case of the credit card. As explained for the latter case, when the carriage is in column 35, a circuit is formed through column 35 commutator contact 424 (Fig. 21g) for energizing relay coil 485. It will be recalled that when a simple or computed credit card was prepared, either contacts 120c or 140c (Fig. 21g) were closed while column 35 was in punching position and the circuit of the X magnet 322 was completed through one or the other of these contacts and relay contacts 485a. However, during readout of a total, neither contacts 120c nor 140c are closed and a different circuit must be provided for the X magnet 322 when the balance is a credit. As explained above, the con-

version magnet 183 has been energized owing to detection of a negative or credit balance in the total bank ACC—T. With magnet 183 energized, its contacts 183x (Fig. 21g) are shifted. Magnet 5 PM is also energized through contacts 188b at this time, and its contacts PMb are closed. The column 35 commutator contact is plugged not only to coil 485 but also to a coil 490. Thus, with the card in column 35 position, contacts 490a 10 are closed. The latter contacts are in series with the hand switch 491 which is set in minus position when it is desired to identify credit balance cards by an X hole in column 35. If it were desired, instead, to punch an X hole in column 35 15 of debit total cards, switch 491 would be set in plus position. With switch 491 in minus position, and card column 35 in punching position, the following circuit forms:

20 *Negative balance card X punching (column 35).*—Line side 453, contacts 403, 451a and 370, connection p1, contacts PMb, the left side of now-shifted contact 183x, switch 491, contacts 490a, the X key magnet 322, and through resistance to line side 452.

25 The energization of the X magnet 322 results in punching an X hole in column 35. At the same time, the digit selected by the total readout circuit for card column 35 is punched in this column through the regular punch selecting circuit extending through selected key contacts 28p and contacts PMa.

ZERO BALANCE OPERATIONS

30 When the balance in the total bank is zero and the operator, nevertheless, initiates total taking operation, means are provided to prevent formation of any circuits through total emitter E—T. Thus, the first column of the total section will remain set at the typing position, indicating to the operator that the balance is zero. It will be recalled that the read out of a zero, when not preceded by a significant digit, from columns 8 to 3 of the total bank is routed through the normally closed side of contacts 167b to the space solenoid 30—SP to effect intraline or character spacing of the bill. When the balance is 1 to 9 cents, the "0" in column 2 is nevertheless read out into solenoid 30—0, as explained previously, to type "0" in the tens of cents column of the total section. However, when the balance is zero in all the columns, then the read out of zeros from any column, including cents columns 1 and 2 is prevented. Therefore, space bar operations will not occur and the first column of the total section will remain at typing position. Since neither space bar nor digit key operations occur, the card will stay in column 33 position and will not be punched further. The error key EK will then be operated to cause eject of the card and insertion of a new card.

35 60 To determine whether the balance is zero, a so-called zero test shot is made before the total read out begins at point "8" of a readout cycle (Fig. 20b). It will be recalled that when the typewriter carriage was tabulated to the total field and the total key depressed, the coil 187 circuit (Fig. 21f) was completed. Coil 187 closes contacts 181d and, when cam contacts R11 close, a circuit is formed through the "0" test multi-contact magnet 210 as follows (bottom of Fig. 21f):

40 65 "0" balance test magnet circuit.—Line 101, contacts R11, contacts 181d, plural coil magnet 210, line 102.

70 75 Magnet 210 operates its several relay contacts,

and if columns 1 to 8 of the total bank all read "0", then the following circuit forms (start with Fig. 21a):

"0" balance detecting circuit.—Line 101, relay contacts 210a, wire 211 (turn to Fig. 21b), the first column "0" segment, the + brush engaged therewith, the + collector ring, contacts 210b, the + collector ring of the column 2, its + brush, the "0" segment of the column 2, contacts 210c, the "0" segment of the column 3, the + brush of column 3, its + ring, contacts 210d, the + ring of the column 4, its + feeler, its "0" segment, the "0" segment of the column 5, its + feeler, its + ring, contacts 210e, the + ring of the column 6, its + feeler, its "0" segment, the "0" segment of the column 7, its + feeler, its + ring, contacts 210f, the + ring of the column 8, its + feeler, its "0" segment, contacts 210g, wire 212 (turn to Fig. 21e), coil 191, line 102.

As may be noted from Fig. 21b, contacts 210h, i, j, and k are, respectively, inserted between the "0" segments of the first and second columns, between the "0" segments of the third and fourth columns, between the "0" segments of the fifth and sixth columns, and between the "0" segments of the seventh and eighth columns of the total bank. When magnet 210 is energized, it opens these contacts 210h, i, j, and k, insuring the "0" balance detecting circuit being routed, seriatim, through the + collector rings of all the columns. If, for example, the "0" segments of the first and second columns were not disconnected by the opening of contacts 210h, then the circuit would go from the "0" segment of the first column directly to the "0" segment of the second column, and through contacts 210c to the "0" segment of the third column, thus skipping the "0" test for the second column.

When the "0" balance detecting circuit is formed, coil 191 is energized, closing contacts 191b (Fig. 21e) to form a stick circuit for the coil through cam contacts R10, which remains in effect for the rest of the first readout cycle. During the succeeding readout cycles, the circuits of magnet 210 and of coil 191 are repeated.

Coil 191, upon energization, opens contacts 191a, in the common side of the total readout circuits (see Fig. 21b). As a result, the space bar solenoid circuits, normally provided when the column preceding a significant figure reads "0", do not form, the card is not punched in the amount section, and the bill remains stationary, with the left-hand column of the total section resting at typing position. As the carriage has not been tabulated, switch SW-#3 remains in position "10", coil 187 remains energized, and the clutch circuit is maintained through its contacts 187b, causing continuous running of the calculator unit. All these are indications that the balance reading is zero. This is of particular value when the indicator wheels 47 of the total bank are not visible to the operator.

It may be noted that the purpose of normally open contacts 210c between the "0" segments of columns 2 and 3 of the total bank is to disconnect the "0" segments of columns 8 to 3 from the "0" segments of columns 1 and 2, except when all the columns read "0" and the "0" balance detecting circuit forms. The purpose of the normal break between the "0" segments of the second and third columns is to cause a "0" in the tens of cents order or second column of the total bank to be read out and typed even if all the dollars columns read "0", provided, however,

that there is a significant figure in the units of cents column. Thus, with all the dollars columns standing at "0" and the units of cents column having a significant figure, the contacts 5 167b (Fig. 21a) will be in normal condition with its right-hand side closed, routing the "0" readout circuits of the dollars columns to the space bar solenoid 30—SP. However, if the second column also reads "0" the following readout circuit 10 will be established (Fig. 21b):

"0" debit readout of second column of total bank.—As in the other total readout circuits to spot "2" of the emitter E-T, the normally closed side of the connected 201a contacts, the + ring 15 of the column 2, the + brush thereof, the "0" segment thereof, normally closed contacts 210h, the "0" segment of the units column, wire 211 (turn to Fig. 21a), contacts 190c of the now-energized total control magnet 190, the normally closed side of inversion relay contacts 193c, connection b—11, solenoid 30—9, connection b—9, coil 167, line 102.

Thus, the lack of a significant figure in the dollars columns of the total bank does not prevent the read out and typing of a "0" in the dimes column preceding a significant figure in the units of cents column.

The "0" debit readout circuit of column 1 of the total bank is through a similar circuit, extending from total emitter spot "1", through the normally closed side of inversion relay contacts 193b to the + collector ring of column 1, the + brush and "0" segment thereof, wire 211, and from there on as in the preceding circuit.

When the total bank carries a credit or minus balance, then the inversion relay magnet 193 is energized during total read out, and contacts 193b and c are in shifted condition, preventing formation of the above "0" debit readout circuits through columns 1 and 2. The "0" credit readout circuit of column 1 has been traced previously. If column 1 has a credit value "0", then the tens complement of the credit value in column 2 also is read out, and if column 2 reads "0", then typing and punching of a zero result, as previously explained. However, if column 1 has a significant digit, then the "9" complement of the column 2 value is read out, and if column 2 reads "0", the following circuit forms (Fig. 21b):

"0" credit read out of column 2 of total bank.—As in the previous total readout circuits to emitter spot "2", then through the normally closed side of contacts 201a, the + collector ring 55 of column 2, the + brush thereof, the "0" segment engaged thereby, contacts 210h, the "0" segment of column 1, wire 211 (turn to Fig. 21a), total relay contacts 190c, the right now-closed side of inversion relay contacts 193c, a wire 213 60 (return to Fig. 21b), the jumper to the lower, now-closed side of inversion relay contacts 193a—9, connection b—20 (continue with Fig. 21a), the key solenoid 30—9, connection b—9, coil 167, line 102.

Thus, when column 1 has a significant credit digit and column 2 reads "0", then the "9" complement of the column 2 digit is read out.

PRODUCT RESET SWITCH

The product bank ACC-P may be reset at any time, at the will of the operator, by throwing the switch SW-PR (Figs. 1 and 21a) to dotted line position (Fig. 21a).

When switch SW-PR is closed, the following circuit forms (begin with Fig. 21b):

Alternative reset of product bank.—Line 102, product bank reset magnet RM—P, connection b—50 (turn to Fig. 21a), the dotted line position of switch SW—PR, connection b—52 (continue with Fig. 21e), coil 215, cam contact A12, line 101.

Coil 215 closes contacts 215a, in parallel with contacts RHd, to form a circuit, similar to clutch circuit #1, through the clutch magnet 40 (Fig. 21f), setting the calculator shaft 36 in operation. The energization of magnet RM—P then causes resetting of the product bank.

If the switch SW—PR is thrown to alternative position while the calculator unit is effecting multiplication, the multiplication operation will be stopped immediately and the product bank reset. For this purpose, coil 215 closes contacts 215b (Fig. 21e), connecting the common of switch SW—#2 to the "4" spot thereof, as a result of which the release magnet SWR—2 circuit, in which coils 131 and 153 are included, is formed, causing restoration of the switch SW—#2 to home position, while the coil 131 opens contacts 131a common to the stick circuits of the retainer relay coils 114 (Fig. 21c). Thus, the value retaining means is cleared, and the multiplying operation, which requires energization of column shift magnets 128 (Fig. 21e) is interrupted. The resetting of the product bank is effected by the energized magnet RM—P. The purpose of throwing switch SW—PR during multiplying operation is to reset the product bank and clear the value retainer means upon discovering an error after multiplication has begun. If the error is discovered after multiplication has been completed but before the auto typing of the product has begun, then the coil 160 stick circuit will have been closed but the coils 149 and 161 circuit still will be open. Then, by operation of switch SW—PR, the product bank will be reset and, during the resetting operation, reset switch RMa—P will open to break the coil 160 stick circuit (Fig. 21e), preventing the initiation of the auto read out of the product.

ERROR KEY CONTROL

Operation of the error key EK (Fig. 1) initiates a card eject and feed cycle in the punch unit. The key is operated also to clear the value retainer bank if an error is discovered in the manual typing within the lot number, quantity, price, or credit sections. The error in the manual typing of a simple credit item in the credit section must be discovered before the last digit is typed, as otherwise, magnet RH will be energized and will close contacts RHd (Fig. 21f) to initiate entry of the credit value into the total bank, as may be understood from the description of the simple credit entry given hereinbefore. The operation of the error key causes deenergization of any value coils 114 which may have been energized before the error key was depressed. The error key operation also causes the switch SW—#1 to be restored to home position. When the error key is depressed, it opens the normally closed left side of contacts EKa and closes the normally open side thereof (Fig. 21a). The opening of the normally closed side of contacts EKa breaks the value coil stick circuits which may have previously been formed, deenergizing all the value coils 114. The closing of the normally open side of contacts EKa forms the following circuit (Fig. 21a):

Release magnet SWMR—1 circuit #2.—Line 101, connection b—34, the right, now closed side

of contacts EKa, connection b—35 (turn to the bottom of Fig. 21b), the normally closed side of contacts RHc, switch contacts SWa—1 (closed when the feeler of switch SW—#1 advanced from home position), release magnet SWR—1, line 102.

A circuit is formed, coincidentally with the above circuit, through coil 143 as previously traced.

10 Energization of magnet SWR—1 restores switch SW—#1 to home position.

Coil 143 energized by the parallel circuit opens contacts 143a (Fig. 21e) in coil 111 circuit #2 causing opening of contacts 111a (Fig. 21a) in the key coils circuit, coil 140 circuit, and coil 120 circuit, preventing further entry of price values into the value retainer bank.

Coil 143 also closes contacts 143b (Fig. 21g) to energize the release key solenoid 322—R, the result of which is the initiation of a card eject and feed cycle, as described before.

When the operator has already typed the price and quantity values and multiplication has begun but is not completed, the operation of the error key opens the stick circuits of the value coils, as explained above, causing contacts 118b (Fig. 21d) to open. Further, since magnet RH is deenergized, contacts RHc in the circuit of magnet SWM—2 (Fig. 21e) reopen, prevent further advance of the switch SW—#2, and multiplication ceases. Contacts RHd (Fig. 21f) open, breaking clutch circuit #1, and the cycles of shaft 36 stop when the clutch shunt circuit breaks. The product bank is then reset by operation of switch SW—PR.

While there has been shown and described and pointed out the fundamental novel features of the invention as applied to a single modification, it will be understood that various omissions and 40 substitutions and changes in the form and details of the device illustrated and in its operation may be made by those skilled in the art without departing from the spirit of the invention. It is the intention therefore to be limited only as 45 indicated by the scope of the following claims.

What is claimed is:

1. The combination with a recording unit having means to record data on a sheet and data selecting means therefor, of a separate 50 card punch unit having punches to punch columns of a record card with data designations, column-by-column punch selecting means controlled by said data selecting means concomitantly with and according to selection of data for recording, and means for delaying effectiveness of the data selecting means in selecting data for recording on said sheet until a predetermined card column and the punch selecting means are in correlation with one another.

60 2. The combination with a recording unit having means to record data on a sheet and data selecting means therefor, of a separate card punch unit having punches to punch columns of a record card with data designations, punch 65 selecting means, mechanism for effecting relative movement between the punch selecting means and the card to effect column-by-column correlation between the card and punch selecting means, means controlled by the data selecting means for controlling operation of the punch selecting means according to the data selected for recording, and means rendered effective under control of said mechanism for enabling 70 the data selecting means to select data for recording on the sheet only when a predetermined 75

card column and the punch selecting means attain correlation with one another.

3. The combination with a typewriter or the like to type characters successively on a sheet and character selecting means therefor, of a separate card punch unit having punches to punch columns of a record card with character representations, column-by-column punch selecting means controlled by said character selecting means concomitantly with and according to the successive typing of characters, and means for delaying effectivity of the character selecting means in selecting characters and causing typing thereof until a predetermined card column and the punch selecting means are in correlation with one another.

4. The combination with a typewriter or the like to type characters successively on a sheet and character selecting means therefor, of a separate card punch unit having punches to punch columns of a record card with character designations, column-by-column punch selecting means, mechanism for effecting relative movement between the punch selecting means and the card to effect column-by-column correlation between the punch selecting means and the card, means controlled by the character selecting means concomitantly with and according to the typing of characters for operating the punch selecting means, and means under control of said mechanism for delaying effectivity of the character selecting means in causing typing of characters until a predetermined card column and the punch selecting means are in correlation with one another.

5. The combination with recording means, operating means therefor, and character selecting means for causing the operating means to operate the recording means to record selected characters, of a card punch unit including punches for punching columns of a record card with character representations, punch selecting means controlled by the character selecting means concomitantly with the recording of the selected characters, a card supply, mechanism for feeding cards from the supply to the punches, and means controlled by depletion of the cards for rendering said operating means for the recording means ineffective.

6. The combination with recording means, operating means therefor, and character selecting means for causing the operating means to operate the recording means to record selected characters, of a card punch unit including punches for punching columns of a record card with character representations, punch selecting means controlled by the character selecting means concomitantly with selection of characters for recording for effecting selection of punches for punching of the corresponding character representations, mechanism for locating a card in punching position, means detecting failure of a card to be located properly in punching position, and means controlled by the detecting means, upon detecting failure of a card to be located properly in punching position, for rendering the operating means of the recording means ineffective.

7. The combination with a recording unit having means to record characters on successive lines of a sheet, character selecting means for the recording means, and devices operable to cause line spacing of the sheet, of a separate card punch unit having punches to punch a record card with character representations, 75

punch selecting means controlled by the character selecting means concomitantly with selection of characters for recording, and means in the punch unit for causing operation of said devices to effect line spacing of the sheet with respect to the recording means.

8. The combination with recording means to record characters on lines of a sheet, character selecting means for the recording means, and devices operable to cause line spacing of the sheet, of a separate card punch unit having punches to punch a record card with character representations, punch selecting means controlled by the character selecting means concomitantly with the selection of characters for recording, mechanism for moving the card with respect to the punches, and means controlled by said mechanism for causing operations of said devices to effect line spacing of the sheet with respect to the recording means.

9. The combination with recording means to record characters on lines of a sheet, character selecting means for the recording means, and devices operable to cause line spacing of the sheet, of a separate card punch unit having punches to punch a record card with character representations, punch selecting means controlled by the character selecting means concomitantly with selection of characters for recording, mechanism for ejecting a card from punching position, and means controlled by said mechanism for effecting operation of said devices to cause line spacing of the sheet.

10. The combination with recording means to record data on lines of a sheet and devices operable to cause line spacing of the sheet, of a card punch unit having punching means to punch data representations into a record card, mechanism for causing a card to be fed to the punching means, and means for causing conjoint operation of the said mechanism to feed a card to the punching means and of said devices to cause line spacing of the sheet so as to place a new line of the sheet in recording position coordinate with the placing of a new card in punching position.

11. The combination with typing means to type items on successive lines of a sheet and devices operable to cause line spacing of the sheet, of a card punch unit having means to punch records with data representations, means for presenting records, one at a time and in succession, to the punching means, and means to conjointly initiate operation of the record presenting means and operation of said devices so as to cause a new record to be presented to the punching means for each new line of the sheet line-spaced to typing position.

12. The combination with recording means to record data in different sections of a sheet depending on the classification of the data, data selecting means for selecting the data to be recorded, and section-selecting means for selecting a section of the sheet to receive the data, of a card punch unit having punches and punch selecting means to control the punches for punching data and classification designations in columns of a record card, means controlled by the data selecting means for causing concomitant operation of the recording means and the punch selecting means according to selected data, and means controlled by the section-selecting means for causing operation of the punch selecting means to select a classification designation to be punched.

13. The combination as defined in claim 12, wherein mechanism is provided to effect column-by-column correlation between the punch selecting means and the card and wherein means under control of said mechanism selects the card column to be punched with the classification designation.

14. The combination as defined in claim 12, wherein mechanism is provided to effect column-by-column correlation between the punch selecting means and the card, wherein a plurality of section-selecting means are provided, each to select a different section of the sheet to receive the data recording, and wherein means under control of said mechanism and each section selecting means selects a different column of the card to be punched with a classification designation depending on which section-selecting means is effective.

15. The combination with a recording unit having means to record data which may be of different classifications, data selecting means, and classification determining means, of a separate card punch unit having punching means to punch a record card with data and classification designations, punch selecting means, means controlled by the data selecting means for concomitantly selecting data to be recorded and operating the punch selecting means to select punches for the punching of corresponding data representations, electrical means selectively conditioned under control of the classification determining means, and means under control of said electrical means when conditioned according to a particular data classification for causing the punch selecting means to select a classification designation to be punched in a card column.

16. The combination with a typewriter or the like having means to type the digits of an amount in columns of a sheet and column spacing means to effect column spacing between the sheet and the typing means, of amount selecting means and a card punch unit having means to punch zero and significant digit designations in columns of a record card, and means controlled by the amount selecting means for concomitantly controlling selection of the punching means for punching of designations of the digits of an amount and operation of the typing means to type said digits and including means for causing selection of the punching means for punching of zero designations preceding the first significant digit designation and concomitantly causing operation of the column spacing means without accompanying typing operation.

17. In combination, a recording unit having means to support a sheet and means to print data on said sheet, data selecting means therefor, a separate punching device having punches to punch data designations into a record medium, means to locate the record medium and punches with respect to one another in punching position for the punching of data designations related to the data to be printed, punch selecting means controlled by the data selecting means according to the data selected for printing, and means to delay operation of the data selecting means in selecting data for printing until the record medium and punches have been located with respect to one another in said punching position.

18. In a combination calculating, recording

and punching machine wherein a derived amount is obtained by calculation, recording means to record said amount on a sheet, punching means to punch a record medium with designations related to said amount, amount manifesting means automatically settable according to the derived amount, devices controlled thereby for concomitantly selecting the amount to be recorded and the related designations to be punched, and

10 means for delaying operation of said devices, after the amount manifesting means have been set, until the record medium and punching means are in proper correlation with one another.

15 19. In combination, recording means to record data on a sheet, punching means to punch a record medium with related data designations, settable multidenominational order amount manifesting means, automatic means controlled by the amount manifesting means, after the setting thereof has been completed, for causing the recording means to record the manifested amount and the punching means to punch the related designations, and means to delay operation of 20 said automatic means pending proper positioning of said sheet with respect to the recording means.

25 20. The combination as defined in claim 19, and means for further delaying operation of 30 said automatic means until the record medium also is in proper punching position.

21. In combination, a punching unit having punches to punch data and classification designations into a field of columns of a record medium, a plurality of data manifesting means, means to select the punches for punching data designations into the same field of columns of the record medium under control of one or another of the data manifesting means, means to 35 select which data manifesting means is to control the punch selection, and means to punch a classification designation in the record medium when one of said data manifesting means is in punch-selection control.

40 22. In combination, a punching unit having punches to punch columns of a record medium with classification and data designations, column-by-column punch selecting devices, mechanism for effecting relative movement between the record medium and the punch selecting devices to effect column-by-column correlation therebetween, data selecting instrumentalities to select data of a particular classification and to control the punch selecting devices according to the data, means to cause the punch selecting devices when in correlation with a predetermined column of the record medium to effect punch selection for a classifying designation, and manual control means optionally and preliminarily operable, before the predetermined column and punch selecting devices are in correlation, for determining that the first-named means is to be effective.

45 23. The combination as set forth in claim 22, said first-mentioned means including means controlled by the aforementioned mechanism when said predetermined column and the punch selecting means are in correlation with one another.

CLAIR D. LAKE.
FRANCIS E. HAMILTON.

CERTIFICATE OF CORRECTION.

Patent No. 2,285,289.

June 2, 1942.

CLAIR D. LAKE, ET AL.

It is hereby certified that error appears in the printed specification of the above numbered patent requiring correction as follows: Page 31, first column, line 15, claim 14, for the word "section" read --punch--; and that the said Letters Patent should be read with this correction therein that the same may conform to the record of the case in the Patent Office.

Signed and sealed this 28th day of July, A. D. 1942.

Henry Van Arsdale,

(Seal)

Acting Commissioner of Patents.
